CODED TRACK CIRCUIT SIGNALING
SYSTEMSedgwick N. Wight, Rochester, N. Y., assignor
to General Railway Signal Company, Roche-
ster, N. Y.

Application May 2, 1941, Serial No. 391,454

35 Claims. (Cl. 246—33)

This invention relates to signaling systems for railroads and it more particularly pertains to block signaling systems of the absolute permissive block type for single track railroads.

In the well known type of absolute permissive block signal systems such, for example, as in the system shown in my Patent No. 1,294,736, dated February 18, 1919, it is assumed that the passing sidings are located far enough apart to provide sufficient safe braking distance for opposing trains to come to stop after having encountered intermediate stop signals in the stretch of single track between sidings in case of simultaneous entry of two opposing trains into such stretch of track. The braking distance must be provided beyond such intermediate signals because, under conditions of simultaneous entry of opposing trains into such stretch of track, the trains would encounter no caution indication to warn the trainmen of the stop condition of the first of the intermediate signals to be encountered, and therefore the minimum distance between opposing intermediate signals must be double braking distance. The increased speed of the present trains and specific conditions encountered in present practice presents the problem as to how absolute permissive block signaling can be safely provided for short stretches of single track between sidings.

An object of the present invention is to provide an absolute permissive block signaling system employing coded track circuits, without the use of line wires, that can be readily adapted to a short stretch of track as well as a long stretch of track between sidings to cause, in case of simultaneous entry into such stretch of track by two opposing trains, each of such opposing trains will encounter a caution signal prior to its leaving the siding section, and thereby have sufficient warning to bring the train to a stop short of the first intermediate signal for that direction of traffic. Such a mode of operation provides for safe operation of trains through a stretch of single track between sidings having as few as two blocks. It is desirable, as provided by the present invention, that such restrictive caution indications be provided for opposing trains, but that less restrictive signaling be provided for following trains.

In accordance with the present invention each block has a coded track circuit, and each coded track circuit has at each end a code transmitter and a code receiver. The various code transmitters can be defined as being of two different types, one type being a "driven" code transmitter,

and the other type being an "inverse" code transmitter. A "driven" code as used in this description is a code repeated from a power driven coder or oscillator having the length of its im-

5 pulses and the number of impulses per minute determined by the character of such coder or oscillator, while an "inverse" code is made up of impulses synchronized to energize a track circuit during the deenergized or "off" periods of a 10 driven code transmitted from the opposite end of the track section to provide duplex code transmission for governing signals for both directions of traffic. In most coded track circuit systems of this character the use of the inverse code is 15 limited in that its code rate must be the same as the code rate of the driven code.

Another object of the present invention, using a driven code as a carrier at a given number of 20 impulses per minute, is to provide for the transmission of any selected one of several inverse codes, such codes being made distinctive because of the polarity of the impulses used and the frequency of occurrence of impulses of a particular polarity, the impulses of such particular polarity being spaced at times by a selected number of 25 blank periods in the inverse code. By the number of distinctive inverse codes thus made available for use, it is provided according to the present invention that all desirable signal controls 30 for a given direction of traffic can be transmitted through the track circuit in advance of each signal under the various traffic conditions by use of inverse codes.

Another object of the present invention, main- 35 taining the impulsion of a track circuit to provide a carrier for the inverse code at a given rate, is to provide that such carrier can transmit any selected one of several driven codes, such codes being made distinctive because of the po- 40 larity of the impulses employed for the carrier, and the frequency of occurrence of impulses of a particular polarity, the impulses of such par- 45 ticular polarity being spaced at times by im- pulses of the opposite polarity. It is therefore provided that all desired signal controls for a given direction of traffic can be transmitted through the track circuit in advance of each signal under the various conditions of traffic by use of a driven code, and yet maintain a given non- 50 polar rate of transmission of the driven code impulses so as to constitute a carrier for any selected one of the various inverse codes used for transmission through the track circuit for the opposite direction of traffic.

Another object of the present invention is to

provide impulse polarity selecting means for each of the driven and inverse code transmitters whereby impulses of one polarity in the code transmitted can be spaced by a selected number of impulses of the opposite polarity or, in some cases, by a selected number of blank periods in the code.

Other objects, purposes and characteristic features of the present invention will be in part obvious from the accompanying drawings and in part pointed out as the description of the invention progresses.

In describing the present invention in detail, reference will be made to the accompanying drawings in which corresponding reference characters are used to designate corresponding parts throughout the various figures, in which like letter reference characters are used to designate parts having similar features and functions, such parts being generally made distinctive by reason of preceding numerals or by exponents indicative of the particular locations, functions, or rates of code with which such devices are associated, and in which:

Figs. 1A, 1B, 1C, 1D and 1E show diagrammatically the codes transmitted through the track circuits for the control of the various signals for this embodiment of the present invention in accordance with various assumed traffic conditions; and

Figs. 2A, 2B, 2C, 2D, 2E and 2F, when placed end to end, illustrate in detail the manner in which the present invention is applied to the control of signals for a typical stretch of track including a passing siding and a stretch of single track between passing sidings.

Rather than attempting to show the specific construction and arrangement of parts that would be employed in practice in accordance with the present invention, the illustrations are arranged to show diagrammatically in a simplified manner the circuits employed in order to facilitate the disclosure of the invention as to its mode of operation. Thus, symbols are employed in the conventional manner for the various devices. Relay contacts not shown directly beneath the relay with which they are associated can be readily identified as of such relay by the relay reference character above such contacts, such arrangement being provided in the conventional written circuit manner.

As a simplification of the illustrations, symbols are used in some cases to indicate connections to the terminals of batteries or other sources of electric current instead of showing all of the wiring connections to the terminals of such batteries. The symbols (+) and (-) are therefore employed to indicate the connection to the positive and negative terminals respectively of suitable batteries or other sources of direct current, and the circuits with which those symbols are used always have current flowing in the same direction. The symbols (B+) and (B-) are used to indicate connections to the opposite terminals of a suitable battery or other direct current source which has a central or intermediate tap designated (CN), and the circuits with which those symbols are used may have current flowing in one direction or the other dependent upon the particular (B+) or (B-) terminal used in combination with the intermediate tap (CN). If alternating current is to be used instead of direct current, the polarity symbols employed are to be considered as instantaneous relative polarities.

For the purpose of simplifying the description

of the present invention, reference is made from time to time to functions common to all parts of a similar character by use of the letter reference characters without exponents or preceding numerals. It is to be understood that such a reference applies to any parts designated in the drawings by reference characters that are similar except for the preceding numerals or the exponents associated therewith.

10 With reference to Fig. 1A, the track layout chosen for this embodiment of the present invention consists of a main stretch of track divided into blocks and having passing sidings 23, 24, 25 and 26 spaced short distances apart by stretches of single track. Although only two blocks are provided between passing sidings, such, for example, as the blocks having track sections 10-11T and 12-13T between the sidings 24 and 25, it is to be understood that a greater number of blocks can be provided between passing sidings in accordance with the requirements of practice.

15 It is assumed in this embodiment of the present invention that the passing sidings are connected at their ends by hand-throw switches to the main track, and that each track switch is provided with the conventional proper fouling protection and with a circuit controller for repeating the positions of the track switch.

20 A signal is provided for governing entrance to each of the blocks for each direction of traffic. That is, for example, the signals 8, 10, 12 and 14 are provided for governing entrance respectively to track sections 8-9T, 10-11T, 12-13T and 14-15T for governing east bound traffic (to the right). As an example of the signals provided for governing west bound traffic, it will be noted that signals 13, 11, 9 and 7 are provided for governing entrance respectively to track sections 12-13T, 10-11T, 8-9T and 6-7T.

25 The symbols used for illustrating the various signals are to be considered as conventional symbols of the indications such signals can display or do display under certain traffic conditions, rather than illustrating the particular type of signals employed, as it is to be understood that various types of signals can be used with the system provided by the present invention. The symbols employed do not take into consideration the provision of approach lighting for color light signals as provided in this embodiment, but rather indicate the condition of the signals as if approach lighting were not provided. The signals employed in this embodiment of the present invention are of the type having individual color lamp units, one unit providing a green indication for clear, another unit providing a yellow indication for caution, and a third unit providing a red indication for danger or stop. It is believed that it will be readily apparent to those skilled in the art how other well known types of signals such, for example, as searchlight signals, position light signals and semaphore signals can be employed.

30 Each of the blocks of this embodiment of the present invention has a single track circuit of the coded type, the coding being normally effective, and a driven code being transmitted through each track circuit for the control of the west bound signal at its right-hand end, and an inverse code being transmitted through each track circuit for the control of the east bound signal at its left-hand end.

35 Each track circuit includes at each end thereof a track battery, a contact of a code transmitter relay, and one or more code receiving relays.

At the end of each of the track circuits where it is desired to use both polarities for track feeds, the track battery has a center tap to provide for polarization of the track circuit.

A code following relay TA is connected in the track circuit at each end of each block so as to be operative in response to the energization of its track circuit from the opposite end of a particular polarity, each of such relays TA having a polar structure to allow the picking up of that relay only when it is energized with such polarity. It is therefore provided that each of the relays TA can be picked up only when the lower rail of the main track of the track layout is energized with a positive polarity from the opposite end of the track circuit.

In addition to the code receiving relay TA connected in each end of the track circuits is a neutral code following relay TB which is picked up on each impulse of a code transmitted from the opposite end of that track circuit, irrespective of the polarity of energization of such relay. Under conditions where a neutral relay TB is not required except for approach control an approach relay AP connected in series with the track battery can be used as illustrated in Fig. 2E. Such approach relay is picked up only when its track section is occupied by a train.

An impulsing oscillator 180CT is provided for the left-hand end of each of the blocks for forming the carrier impulses for the driven and inverse codes. Although the relays 180CT are assumed in this embodiment to be of the oscillatory type such, for example, as disclosed in the patent to P. N. Bossart, Patent No. 1,858,876, dated May 17, 1932, it is to be understood that other types of impulsing means such as motor driven impulsers can as well be used. Each oscillatory impulser 180CT used for this embodiment of the present invention provides "off" and "on" periods of relatively equal length, and provides impulses at a given rate of 180 impulses per minute.

At the left-hand end of each of the track circuits is a driven code transmitter comprising a stepping relay bank for selecting the polarity of the impulses to be transmitted, and a polar neutral code repeater relay CP for pulsing the track circuit to transmit impulses of the polarities selected by the stepping relay bank. The number of relays in a stepping bank is dependent upon the number of different codes to be selected for transmission under the various traffic conditions. That is, each of the stepping relay banks includes a code execution relay CEX which directly repeats the oscillator for that end of the track circuit for the transmission of a driven code composed of all positive impulses, and each of the stepping relay banks includes relays 90C and 90CA for causing the application of negative impulses to the track circuit when it is desired to transmit a code having alternately (+) and (-) impulses. The numeral prefix 90 in the reference characters 90C and 90CA indicates that those relays are used when it is desired to transmit a code having impulses of a particular polarity transmitted at a rate of 90 impulses per minute. For certain of the track circuits, when it is desirable to provide for the transmission of an additional code in which the (+) impulses are spaced by two (-) impulses, the stepping relay bank also includes relays 60C and 60CA which are used to space the positive impulses in such a manner as to provide for the transmission of (+) impulses at the rate of 60 impulses per minute and yet space such impulses by (-) char-

acters in order to maintain the carrier impulse rate of 180 impulses per minute. The stepping relays are all relatively quick acting so that they can be picked up or dropped away as required during single "off" or "on" periods.

At the right-hand end of each of the track circuits is an inverse code transmitter comprising a stepping relay bank for selecting the polarity of the impulses to be transmitted, and an inverse code transmitter relay CP for pulsing the track circuit to transmit impulses during the "off" periods of the driven code of polarities selected by the stepping relay bank for that end of the track circuit. Such relay bank includes a relay CEX which is energized for each impulse to be transmitted, relays 90C and 90CA for providing the transmission of (+) impulses spaced by blank periods to provide a rate of 90 impulses per minute, and under conditions when another code is required, the stepping bank for the inverse code transmitter includes relays 60C and 60CA which provide for the transmission of (+) impulses spaced by two successive blank periods to provide a rate of 60 impulses per minute.

Suitable transformers are provided for decoding the impulses received at each end of each of the track circuits, the transformers TF being provided for the energization of H relays used for the control of the signals in accordance with the traffic conditions immediately in advance thereof, and such transformers being effective to provide energization for a tuned circuit including a condenser and a transformer TFA to provide for the control of a relay D. A relay D is provided for each end of each of the blocks, and it is energized only upon the reception of a 180 code composed of all (+) characters. In a similar manner for certain of the block ends, an additional tuned circuit is provided including a transformer TFC and a condenser energized from the transformer TF at that end of the track circuit for causing the energization of a relay HA, which is responsive only to the reception of a code at the rate of 90 (+) impulses per minute. Such relay is used primarily in the selection of codes for transmission through the next adjacent block.

A stick relay S is provided for each signal in order to properly distinguish in the selection of codes for transmission between opposing and following train movements.

Suitable slow acting repeater relays TP, HP and APP are used where required for the purpose of repeating quicker acting relays to ride over the "off" periods in the code received, or for other reasons requiring an additional time element in the operation of the system.

It is to be understood that the selection of relays for use in this embodiment of the present invention is made in accordance with the most desirable operating characteristics, dependent in what capacity the relays are to be used. That is, for example, the relays energized by tuned circuits are adjusted, as is the other apparatus associated therewith, to respond only to the desired frequency, and the relays for the stepping banks are adjusted to provide for the transmission of impulses of the most desirable length, the length of the driven code impulses being comparatively equal to the length of the "off" periods, and the length of the inverse code impulses being slightly less than the length of the driven code "off" periods for reasons to be hereinafter pointed out.

Having thus considered the apparatus provided for the system of the present invention, it is believed that the mode of operation of the system

will best be understood upon considering herein-after various typical operating conditions which might be encountered in practice.

OPERATION

General.—With reference to Fig. 1A, it will be noted that, with the track layout unoccupied by a train, a driven code is transmitted through each track circuit from left to right for the control of west bound signals and an inverse code is transmitted from right to left for the control of east bound signals, the direction of transmission of the driven code being indicated by the arrows having solid lines, and the direction of transmission of the inverse codes being indicated by the arrows having broken lines.

Under normal conditions when the track layout is unoccupied by a train, all signals are clear (except that approach lighting renders some of them normally dark) because of the reception of all (+) impulses at a rate per minute the same as the rate of impulsion of the power driven oscillators which for this embodiment of the present invention is assumed to be at a rate of 180 impulses per minute. Therefore, under the conditions illustrated in Fig. 1A each of the signals is cleared because of the reception of a code transmitted through the block in advance made up of 180(+) impulses per minute. The west bound signals are cleared by a 180(+) driven code, and the east bound signals are cleared by a 180(+) inverse code.

The next restrictive code used is a code having alternately (+) and (−) impulses or, in the case of an inverse code, (+) impulses spaced by single blank periods. A signal receiving such a code from the track circuit in advance is put to caution, but such code having been received causes the transmission through the next block in the rear of an all (+) code at a rate of 180 impulses per minute for the clearing of the next signal in the rear.

A further restrictive code is one having the (+) impulses spaced by two (−) impulses or, in the case of an inverse code, (+) impulses spaced by two blank periods. A signal receiving such a code from a track circuit in advance is put to caution, but such code having been received causes the transmission through the next block in the rear of a code having alternately (+) and (−) impulses, or, in the case of an inverse code, (+) impulses spaced by single blank periods.

Under certain conditions it is desired to transmit a code through a track circuit for the purpose of indicating that such track circuit or block is unoccupied by a train without effecting the display of a proceed indication of a signal governing entrance to the block. Such code has all (−) impulses and can also be used, in case of a driven code, to provide a carrier for the transmission of an inverse code through the track circuit in the opposite direction.

Inasmuch as the decoding means provided in accordance with the present invention for distinctively receiving the various codes is responsive only to the reception of (+) impulses, the decoding is effective dependent upon the rate of occurrence of the (+) impulses in the code. Thus, for the purpose of description of the present invention, it can be said that a code having all (+) impulses is decoded as a 180 code, a code having alternately (+) and (−) impulses (or single blank periods for an inverse code) is decoded as a 90 code, and a code having two (−) im-

pulses (or two blank periods for an inverse code) between the (+) impulses is a 60 code, the rates employed being the number of (+) impulses per minute.

Normal conditions.—With reference to Fig. 1A, it will be noted that each of the signals is conditioned to be clear because of the reception of a 180 code for its control, the west bound signals being clear because of the reception of the 180 driven codes and the east bound signals being clear because of the reception of 180 inverse codes. At the left-hand end of each of the blocks, the impulsion of the track circuit is effected by a code repeater relay CP which in turn repeats the code execution relay CEX for that end of the track circuit. When a 180 code is being transmitted, the relay CEX follows the circuit interrupting oscillator 180CT associated therewith.

At the right-hand end of each of the track circuits, under normal conditions, a relay CP provides the impulsion of the track circuit for the transmission of an inverse code in accordance with the pulsing at a 180 rate of the code execution relay CEX for that end of the track circuit. Such relay CEX is pulsed by the neutral code following relay TB connected in the track circuit at that end of the block.

To consider more specifically, as a typical example, how the 180 driven code is applied to a track circuit, with reference to Fig. 2A, under normal conditions, the relay CEX follows the pulsing of the relay 180CT by its energization during each "on" period upon the closing of a circuit extending from (+), including front contact 43 of the oscillator 180CT, front contact 41 of relay 1H, and lower winding of relay CEX, to (−). During each period in which the relay CEX is energized, a circuit is closed to cause the picking up of the code transmitter relay 8CP extending from (B+), including front contact 43 of relay 7TP, front contact 44 of relay CEX, winding of relay 8CP, and back contact 45 of relay 8TB, to (CN). It will be apparent as the description of the invention progresses that the back contact 45 of relay 8TB in the circuit for relay 8CP allows its energization for transmission of an impulse of a driven code only if there is a brief period of deenergization of the track circuit immediately preceding the transmission of each "on" period of a driven code. Such mode of operation provides a check of each inverse code received at that end of the track circuit against foreign current as fully described in the prior application of common ownership of N. D. Preston, Ser. No. 365,065, filed November 9, 1940.

When relay 8CP is picked up due to positive energization, a circuit is closed to cause the picking up of the relays 9TB and 9TA (see Fig. 2B), extending from the positive terminal of the center tap track battery 46 (see Fig. 2A) including polar contact 41 of relay 8CP in its left-hand position, front contact 48 of relay 8CP, the lower rail of track section 8—9T, back contact 49 of relay 9CP, winding of relay 9TA, winding of relay 9TB, and upper rail of track section 8—9T to the center terminal of the track battery 46. The positive or negative energization as used in the description of this embodiment of the present invention is to be understood as the polarity applied at the transmitting end of the track circuit to the lower rail of the track section.

When the neutral code following track relay 9TB is picked up during the "on" periods of the driven code, the closing of front contact 50 (see Fig. 2B) causes the energization of the repeater

relay 9TP which is sufficiently slow in dropping away to be maintained picked up during the "off" periods of the code. Upon the picking up of the relay 9TA during each "on" period, with the relay 9TP energized, energy is applied to the transformer 9TF by a circuit closed from (+), including front contact 51 of relay 9TA, upper portion of the primary winding of transformer 9TF, and front contact 52 of relay 9TP, to (-).

The shifting of the contact 51 of relay 9TA causes a reversal of flux in the transformer 9TF because, when back contact 51 of relay 9TA is closed during each "off" period, energy flows through the primary winding of transformer 9TF in the opposite direction, such circuit being closed from (+), including back contact 51 of relay 9TA, lower portion of the primary winding of transformer 9TF and front contact 52 of relay 9TP, to (-). It is therefore provided that the reversal of polarity in accordance with the shifting of contact 51 causes quick reversals in flux in the transformer 9TF and thus induces alternating current in the secondaries of the transformer which can be used for the selective energization, in accordance with the codes received, of the relays 9H, 9D and 9HA, the relay 9H being energized upon the reception of a 60, 90, or 180 code, relay 9D being energized by a tuned circuit upon the reception of a 180 code, and relay 9HA being energized by a tuned circuit upon the reception of a 90 code.

The relay 9H is a standard type direct current neutral relay made sufficiently slow in dropping away to ride over the periods in the coding of reduced energization. The contact 53 of relay 9TA serves as a rectifier to provide direct current energization for the relay 9H. More specifically, when front contact 53 is closed energy flows from the lower terminal of the secondary transformer winding 54 through a circuit including front contact 53 of relay 9TA, and winding of relay 9H to the center terminal of winding 54. When back contact 53 of relay 9TA is closed energy flows through the winding of relay 9H in the same direction by a circuit extending from the upper terminal of winding 54 including back contact 53, and winding of relay 9H to the center terminal of winding 54.

Each reversal of polarity in the transformer 9TF, when a 180 code is being received, causes energy to flow in the tuned circuit for the relay 9D in an obvious manner, such tuned circuit including the secondary winding 55 of transformer 9TF, the condenser 56 and the primary winding of the transformer 9TFA. Sufficient energy flows through the winding of the relay 9D connected to the full-wave rectifier 57 from the secondary of the transformer 9TFA to cause the energization of the relay 9D only upon the reception of a 180 code. With the relays 9H and 9D picked up, the circuits are conditioned to cause the display of a clear indication by the signal 9, but, under normal conditions, such signal remains dark because of the provision of approach lighting.

If the relay 10TP were deenergized because of the approach of a train to signal 9, a clear indication would be displayed by the energization of a circuit for the green lamp 9G of signal 9, extending from (+), including back contact 67 of relay 10TP, front contact 68 of relay 9H, front contact 69 of relay 9D, and lamp 9G, to (-).

When the relay 9TB is picked up during each "on" period of the driven code received, the closing of front contact 58, under normal conditions,

causes the picking up of the code execution relay CEX¹ upon the energization of a circuit closed from (+), including front contact 58 of relay 9TB, front contact 59 of relay 10H, and lower winding of relay CEX¹, to (-). The picking up of relay CEX¹ closes a circuit for the primary winding of transformer 9TFB extending from (+), including front contact 60 of relay CEX¹, front contact 61 of relay 9TB, and primary winding of transformer 9TFB, to (-). The building up of the flux of such transformer does not cause the picking up of the relay 9CP, however, because such relay has polar characteristics that cause it to respond only upon the collapse of the flux of the transformer 9TFB. Thus, at the end of each of the "on" periods, under normal conditions, the opening of front contact 61 of relay 9TB causes the collapse of the flux in the primary winding of transformer 9TFB, and the induced voltage in the secondary winding of such transformer causes the picking up of the inverse code transmitting relay 9CP for the transmission of an impulse of an inverse code.

The picking up of relay 9CP during each "off" period of the driven code opens the circuit described for an "on" period of the driven code at back contact 49 for the relays 9TB and 9TA, and closes a circuit for the energization of the code following track relays 8TA and 8TB at the opposite end of the track circuit extending from the positive terminal of the center tap battery 62 including front contact 63 of relay 10TP, front contact 49 of relay 9CP, lower rail of track section 8-9T, back contact 48 of relay 8CP, winding of relay 8TB, winding of relay 8TA, and upper rail of track section 8-9T, to the center tap of the track battery 62.

As a result of the energization of the neutral code following relay 8TB (see Fig. 2A) by each inverse code impulse, the relay 8TP is picked up, by the energization of an obvious circuit closed at front contact 45, and such relay is maintained picked up by its slow drop away characteristics to ride over the "off" impulses of the inverse code received.

Reversal of the flux in the transformer 8TF is effected upon the picking up of the relay 8TA during the "on" period of the inverse code upon the opening of an obvious circuit for the lower portion of the primary winding of the transformer at back contact 65 and the closing of a circuit for the upper portion of the primary winding of that transformer extending from (+), including front contact 65 of relay 8TA, upper portion of the primary winding of the transformer 8TF, and front contact 66 of relay 8TP, to (-). The reversal of flux in the transformer 8TF upon the reception of inverse code impulses causes the energization of the relays 8H and 8D in a manner comparable to that described in detail for the energization of the relays 9H and 9D for the opposite end of the block. It is, therefore, provided that the transmission of a driven code through the track section 8-9T conditions the signal 8 (see Fig. 2B) so that it would be clear if approach lighting were not provided for that signal; and at the same time, the transmission of an inverse code made up of all (+) impulses in the opposite direction through that track section conditions the apparatus for control of the signal 8 (see Fig. 2A) so that such signal can be cleared except for the approach lighting control.

It is provided in a similar manner to that which has just been described in detail that, under nor-

mal conditions a driven code having all (+) impulses at a 180 rate is transmitted to the right through each of the track sections to cause the clearing of the west-bound signal governing entrance to that block, and an inverse code at a 180 rate composed entirely of (+) impulses which is transmitted at the same time through that track section in the opposite direction to condition the H and D relays for the east-bound signal governing entrance to that block so that such signal is clear except for approach lighting control.

Passage of east bound train.—To consider the passage of an east bound train, it will be assumed that an east bound train A has entered track section 4—5T as illustrated in Fig. 1B, but that the trackway in advance of such train is unoccupied. The entrance of that train into track section 4—5T causes the restoration to stop of the opposing signals 5 and 7 in accordance with conventional absolute-permissive-block signaling practice, and the opposing signals 9 and 11 governing approach and entrance to the track section 8—9T are put to caution. For the purpose of considering the movement of the east bound train through the track portion having its signal controls illustrated in detail in Figs. 2A, 2B, 2C, 2D, 2E and 2F, it will be assumed for the time being that the entrance of the train A into track section 4—5T causes the transmission of a driven code having all (—) impulses through the track section 6—7T. Upon the reception of such code at the left-hand end of the passing siding 24, the relay 7H is dropped away because such relay is picked up only upon the reception of (+) impulses, but the track repeater relay 7TP for the right-hand end of the track section 6—7T is maintained energized because such relay is energized as a repeater of a neutral code following relay 7TB (not shown) rather than a polar code following relay. Although the control of relays 7H, 7TP and 7TB is not shown, it will be readily apparent that the control of such relays is the same as is illustrated in Fig. 2F for the relays 13H, 13TP and 13TB respectively.

With relay 7H dropped away and relay 7TP picked up, a .60 driven code is selected for transmission through the track section 8—9T to condition the signal 9 to display a caution indication.

To consider how the .60 code made up of (+) impulses spaced by two (—) impulses is formed, assume that the stepping relays are all deenergized during an "off" period in the coding. Under such conditions, the shifting of contact 40 of oscillator 180CT (see Fig. 2A) to its upper position closes a circuit to cause the picking up of the relay 90C, extending from (+) including front contact 40 of the oscillator 180CT, back contact 41 of relay 7H, lower winding of relay 90C and back contact 70 of relay CEX, to (—). When relay 90C is picked up, a stick circuit is closed for its upper winding extending from (+), including back contact 72 of relay CEX, front contact 76 of relay 90C, and upper winding of relay 90C, to (—). Upon the shifting of the contact 40 of the oscillator 180CT to its lower position, a circuit is closed to cause the picking up of relay 90CA extending from (+), including back contact 40 of oscillator 180CT, front contact 71 of relay 90C, and lower winding of relay 90CA, to (—). Upon the picking up of that relay a stick circuit is closed for its upper winding extending from (+), including back contact 72 of relay CEX, front contact 73 of relay 90CA, and upper winding of relay 90CA, to (—).

When contact 40 of oscillator 180CT shifts

again, the closing of front contact 40 causes the picking up of relay 60C by the energization of a circuit extending from (+), including front contact 40 of oscillator 180CT, back contact 41 of relay 7H, front contact 74 of relay 90CA, back contact 75 of relay 7S, lower winding of relay 60C, and back contact 70 of relay CEX, to (—). Upon the picking up of relay 60C, a stick circuit is closed for that relay extending from (+), including back contact 72 of relay CEX, front contact 71 of relay 60C, and upper winding of relay 60C, to (—).

The next time the contact 40 of the oscillator 180CT shifts to its lower position, a circuit is closed to cause the picking up of the relay 60CA extending from (+), including back contact 40 of oscillator 180CT, front contact 78 of relay 60C, and lower winding of relay 60CA, to (—). The picking up of relay 60CA closes a stick circuit for that relay extending from (+), including back contact 72 of relay CEX, front contact 79 of relay 60CA, and upper winding of relay 60CA, to (—).

When the contact 40 of the oscillator 180CT is again moved to its upper position a circuit is closed to cause the picking up of the code execution relay CEX, extending from (+), including front contact 40 of oscillator 180CT, back contact 41 of relay 7H, front contact 80 of relay 60CA, and lower winding of relay CEX, to (—). When relay CEX is picked up, a stick circuit is closed for that relay to maintain it energized until the shifting of contact 40 of oscillator 180CT to its lower position, extending from (+), including front contact 40 of oscillator 180CT, back contact 41 of relay 7H, front contact 81 of relay CEX, and upper winding of relay CEX, to (—). Upon the picking up of relay CEX the relays 90C, 90CA, 60C and 60CA are dropped away because their stick circuits are opened at back contact 72 of relay CEX. The pick-up circuits for the relays 90CA and 60CA are open at that time because those relays are picked up only when the contact 40 oscillator 180CT is in its lower position, and the pick-up circuits for relays 90C and 60C are open at that time because of the opening of back contact 70 of relay CEX. The next time the contact 40 of the oscillator 180CT shifts in its position, the relay CEX is dropped away to complete the restoration of the stepping relays because of the opening of its stick circuit at front contact 40, its pick-up circuit having already been opened upon the restoration of the relay 60CA.

From the above description of the mode of operation of the stepping relay bank, it will be noted that the cycle of operation described included three periods in which the contact 40 was assumed to have been operated to its upper position. During the first of such periods the relay 90C is picked up, and the other stepping relays remain dropped away. Thus, under such conditions, a circuit is closed for the energization of the polar-neutral relay 8CP for transmission of a (—) impulse, extending from (B—), including front contact 82 of relay 90C, back contact 83 of relay 90CA, back contact 44 of relay CEX, winding of relay 8CP, and back contact 45 of relay 8TB, to (CN). The picking up of relay 8CP with its polar contact operated to a right-hand position in accordance with such energization causes the energization of the code following track relays 9TB and 9TA at the opposite end of the track circuit by a circuit extending from the center tap of track battery 46 including the upper rail of track section 8—9T, winding of re-

lay 9TB (see Fig. 2B), winding of relay 9TA, back contact 49 of relay 9CP, lower rail of track section 8—9T, front contact 48 of relay 8CP (see Fig. 2A), and polar contact 47 of relay 8CP in a right-hand position to the negative terminal of track battery 46. The polarity of energization of the relay 9TA in the circuit just described is such as to cause it to be unresponsive to the (—) impulse. The neutral relay 9TB is of course picked up, irrespective of its polarity of energization.

When the contact 40 of the oscillator 180CT shifts to its lower position following the picking up of relay 90C, the picking up of relay 90CA opens the circuit just described for relay 8CP at back contact 83, to cause that relay to drop away for the initiation of an "off" period in the code applied to the track circuit of track section 8—9T. Such "off" period is terminated, however, upon the picking up of the relay 60C responsive to the shifting of contact 40 of the code oscillator 180CT to its upper position. The relay 8CP is then again energized to cause the transmission of a (—) impulse in the track circuit. The circuit closed for the energization of relay 8CP extends from (B—), including front contact 82 of relay 90C, front contact 83 of relay 90CA, front contact 84 of relay 60C, back contact 85 of relay 60CA, back contact 44 of relay CEX, winding of relay 8CP, and back contact 45 of relay 8TB, to (CN).

The shifting of contact 40 of oscillator 180CT to its lower position next causes the picking up as has been described of the relay 60CA, and such relay in picking up opens the circuit just described for relay 8CP at back contact 85 to cause its release to initiate an "off" period in the code being transmitted through the track circuit. Such "off" period is terminated upon the picking up of the relay CEX responsive to the shifting of contact 40 to its upper position, and upon the picking up of relay CEX under such conditions, with the relay 7TP energized, a circuit which has been described is closed to cause the picking up of the polar-neutral code transmitter relay 8CP with its polar contact operated to a left-hand position to close the track circuit as has been described for the transmission of a (+) impulse. The (+) impulse is terminated upon the dropping away of the relay 8CP when the relay CEX is dropped away to complete the restoration of the relays of the stepping relay bank to their deenergized conditions. A cycle of operation has, therefore, been completed in which three impulses have been applied to the track circuit, the first two impulses being of negative polarity, and the third impulse being of positive polarity. It is to be understood that the cycle of operation just described is repeated continuously to cause the transmission of polar impulses so arranged as to provide for the transmission of (+) impulses evenly spaced at a rate of 60 impulses per minute.

With reference to Fig. 2B, consideration will be given to the reception of a 60 code. Although the windings of the relays 9TB and 9TA are both energized during each impulse of the code received, irrespective of polarity, the relay 9TA is picked up, due to its polar characteristics, only upon the reception of (+) impulses, while the neutral relay 9TB is picked up for each impulse of the code received irrespective of polarity. It is, therefore, provided that the contact 51 of relay 9TA is pulsed at a 60 rate to cause the energization of the relay 9H in a manner which has been described, but the relay 9D is dropped away because its tuned circuit which has been de-

scribed is tuned for only a code at a 180 rate. The relay 9HA remains in its deenergized position because its tuned circuit for its energization is responsive only to the reception of a 90 code formed by alternately (+) and (—) impulses.

It is, therefore, provided that, were the approach lighting effective for the signal 9, a circuit would be closed for the yellow lamp 9Y of such signal for a caution indication extending from (+), including back contact 67 of relay 10TP, front contact 68 of relay 9H, back contact 69 of relay 9D, and lamp 9Y of signal 9, to (—).

It will be noted that the reception of a 60 driven code at the right-hand end of the track section 8—9T in no way affects the transmission of an all (+) inverse code back through the track circuit because the impulsion of the inverse code is dependent upon the neutral code following relay 9TB which is energized during each impulse, irrespective of the polarity of such impulse. It is, therefore, provided under the assumed traffic conditions, that a 180 inverse code is transmitted through the track section 8—9T to condition the signal 8 so that it will clear, dependent upon the approach of the train A to provide approach lighting.

It will be noted from the conditions that have just been described that the relay 9H is energized, and relays 9D and 9HA are deenergized, and the track repeater relay 9TP is energized in an obvious manner in accordance with the reception of a 60 code at the right-hand end of track section 8—9T. It is, therefore, provided with the relays thus conditioned that a 90 code will be transmitted through the track section 10—11T to govern the caution indication of signal 11 (see Fig. 2D). Inasmuch as the code transmitted under such conditions is a 90 code rather than a 60 code, the stepping relays 60C² and 60CA² (see Fig. 2C) remain deenergized during the transmission of the 90 driven code.

To consider a cycle of operation of the stepping relay bank for the left-hand end of track section 10—11T, assume the stepping relays all to be momentarily deenergized during an "off" period of the driven code following the transmission of a (+) impulse. Upon the shifting of contact 103 of the oscillator 180CT² to its upper position, a circuit is closed to cause the picking up of relay 90C² extending from (+) including front contact 103 of oscillator 180CT², back contact 104 of relay 9D, back contact 105 of relay 9HA, lower winding of 90C², and back contact 106 of relay CEX², to (—). Upon picking up of that relay a stick circuit is closed for its upper winding including back contact 107 of relay CEX², front contact 108 of relay 90C², and upper winding of relay 90C², to (—).

When contact 103 of oscillator 180CT² shifts to its lower position, a circuit is closed to cause the picking up of the relay 90CA² extending from (+), including back contact 103 of oscillator 180CT², front contact 109 of relay 90C², and lower winding of relay 90CA², to (—).

Due to the energized condition of the relay 9TP for the adjoining track section, a circuit is closed upon the shifting of contact 103 to its upper position for the energization of the code execution relay CEX², such circuit extending from (+), including front contact 103 of oscillator 180CT², back contact 104 of relay 9D, back contact 105 of relay 9HA, front contact 110 of relay 90CA², front contact 111 of relay 9TP, and lower winding of relay CEX², to (—). The picking up

of relay CEX² causes the release of relays 90C² and 90CA² by opening their stick circuits at back contact 107 and opening the pick-up circuit for relay 90C² at back contact 106. The release of relay 90C² opens the pick-up circuit just described for relay 90CA² at front contact 109. The relay CEX² is held up, however, until the shifting to the lower position of contact 103 of oscillator 180CT² by a stick circuit for its upper winding closed from (+), including front contact 103 of oscillator 180CT², back contact 104 of relay 9D, back contact 105 of relay 9HA, front contact 113 of relay CEX², and upper winding of relay CEX², to (-). The restoration of relay CEX² upon the shifting of contact 103 of oscillator 180CT² to its lower position completes the restoration of the stepping relay bank to complete a cycle of operation in which the relays 60C² and 60CA² remain idle and relays 90C², 90CA² and CEX² are used for causing alternately (+) and (-) impulses to be applied to the track circuit.

The polar-neutral transmitter relay 10CP is pulsed alternately with one polarity and then the other in accordance with the operation of the stepping relay bank to apply alternately (+) and (-) impulses to the track circuit 10-11T. That is, upon the picking up of the relay 90C², the relay 10CP is picked up with its polar contacts operated to a right-hand position because of negative energization by a circuit extending from (B-), including front contact 114 of relay 90C², back contact 115 of relay 90CA², back contact 116 of relay CEX², winding of relay 10CP, and back contact 117 of relay 10TB, to (CN).

When relay 10CP is picked up with its polar contact operated to a right-hand position, a (-) impulse is applied to the track circuit of track section 10-11T to cause the energization of the windings of relays 11TA and 11TB (see Fig. 2D) by a circuit closed from the center terminal of track battery 118 (see Fig. 2C) including the upper rail of track section 10-11T, winding of relay 11TB, winding of relay 11TA, back contact 119 of relay 11CP, lower rail of track section 10-11T, front contact 120 of relay 10CP, and polar contact 121 of relay 10CP in a right-hand position to the negative terminal of track battery 118.

When the relay 90CA² is picked up upon the shifting of contact 103 of oscillator 180CT² following the energization of relay 90C², the (-) impulse applied to the track circuit is terminated because of the opening of the circuit for relay 10CP, at back contact 115 of relay 90CA². The next time the contact 103 of oscillator 180CT² shifts to its upper position the picking up of relay CEX² terminates the "off" period of the driven code being transmitted through track section 10-11T by causing the energization of relay 10CP with positive polarity. Relay 10CP is energized under such conditions by a circuit closed from (B+), including front contact 116 of relay CEX², winding of relay 10CP, and back contact 117 of relay 10TB, to (CN). The shifting of polar contact 121 of relay 10CP causes the energization of the track circuit for track section 10-11T with a positive polarity, the track circuit energized being the same as has been described except that the positive terminal of track battery 118 is connected in the circuit instead of the negative terminal due to the polar contact 121 of relay 10CP being operated to its left-hand position.

At signal 11 (see Fig. 2D), the reception of the 90 code causes the pulsing of contact 122 of the

code following track relay 11TA at a 90 rate because such relay follows only the (+) impulses, and as a result of the pulsing of that contact the relay 11H is maintained picked up in a manner comparable to that which has been described in detail for relay 9H, the circuit for relay 11H including back contact 123 of the stick relay 12S for the opposing signal for purposes to be more readily apparent as the description of the invention progresses.

In accordance with the reception of the 90 code, sufficient energy flows through the tuned circuit for relay 11HA including secondary winding 124 of transformer 11TF, condenser 125, and primary winding 126 of transformer 11TFC to cause the relay 11HA to be operated to its energized position. The relay 11D is deenergized because its circuit is tuned only to a 180 rate.

With the relays for the control of signal 11 conditioned as has been described, it is provided that signal 11 would display a yellow caution indication if the approach lighting contact 134 of relay 12APP were closed. Under such conditions the yellow lamp of signal 11 would be illuminated by the energization of a circuit closed from (+), including front contact 134 of relay 12APP, front contact 135 of relay 11H, back contact 136 of relay 11D, and lamp 11Y, to (-).

The neutral code following track relay 11TB follows each impulse of the driven code applied to track section 10-11T, and closes an obvious circuit at contact 127 to cause the energization of the track repeater relay 11TP, such relay remaining picked up during the "off" periods of the code received. The pulsing of contact 128 of relay 11TB causes the picking up of relay CEX³ during each "on" period of the driven code received, by the energization of a circuit extending from (+), including front contact 128 of relay 11TB, front contact 129 of relay 12D, and lower winding of relay CEX³, to (-). Such energization of the relay CEX³ causes the energization of the relay 11CP during each of the "off" periods of the driven code for the transmission of an impulse for the inverse code in a manner comparable to that which has been described in detail with reference to the control of the relay 9CP.

Upon the picking up of the inverse code transmitter relay 11CP during each "off" period of the driven code, a circuit is closed for the transmission of a (+) impulse through the track circuit of track section 10-11T extending from the positive terminal of track battery 130 including back contact 131 of relay 11S, front contact 132 of relay 12H, front contact 119 of relay 11CP, lower rail of track section 10-11T, back contact 120 (see Fig. 2C) of relay 10CP, winding of relay 10TB, winding of relay 10TA, and upper rail of track section 10-11T to the center terminal of the track battery 130 (see Fig. 2D).

It is provided at the location of signal 10 (see Fig. 2C) that the reception of a 180 inverse code causes the pulsing of contact 137 of relay 10TA at a 180 rate to effect the energization of the relay 10H in a manner comparable to that described in detail with reference to the energization of relay 9H, and to cause sufficient energy to flow in the tuned circuit of relay 10D to cause the picking up of that relay. Under such conditions the signal 10 displays a green clear indication because of the energization of a circuit for the green lamp 10G of that signal extending from (+), including front contact 138 of relay 10H, front contact 139 of relay 10D, and lamp 10G, to (-). The signal 10G has been illustrated as being

steadily illuminated, irrespective of the traffic conditions because such signal is an absolute signal and the leaving signal for siding 24. It is to be understood, however, that approach lighting can as well be provided for this signal if it is desirable in practice.

In accordance with a reception of a 90 code for the caution indication of signal 11, the energization of the relay 11HA tuned to such code is effective to select a 180 driven code for transmission through the track section 12-13T for the control of signal 13. To apply such code, with reference to Fig. 2E, the relay CEX⁴ is picked up each time the contact 150 of oscillator 180CT⁴ is closed. The relay CEX⁴ is picked up under each of such conditions by the energization of a circuit extending from (+), including front contact 150 of oscillator 180CT⁴, front contact 151 of relay 11HA, and lower winding of relay CEX⁴, to (-).

The driven code transmitter relay 12CP is picked up with its polar contact operated to a left-hand position for the application of a (+) impulse to the track circuit of track section 12-13T each time the relay CEX⁴ is picked up. Relay 12CP is picked up under such condition by the energization of a circuit closed in accordance with the energized condition of relay 11H, extending from (B+), including back contact 152 of relay 12S, front contact 153 of relay 11H, front contact 154 of relay CEX⁴, winding of relay 12CP, and back contact 155 of relay 12TA, to (CN).

Upon the picking up of relay 12CP with its polar contact operated to a left-hand position, a circuit is closed for the positive energization of the track relays at the opposite end of the track section, extending from the positive terminal of track battery 156, including polar contact 157 of relay 12CP in a left-hand position, front contact 158 of relay 12CP, lower rail of track section 12-13T, back contact 159 (see Fig. 2F) of relay 13CP, winding of relay 13TA, winding of relay 13TB, upper rail of track section 12-13T, and winding of approach relay 12AP (see Fig. 2E) to the center terminal of track battery 156. The approach relay 12AP has such operating characteristics as to provide that it remains dropped away except when an abnormal amount of current flows through the track circuit for track section 12-13T due to the presence of a train in such track section.

With reference to Fig. 2F, the relay 13TA is picked up during each impulse of the code received as the code received is a 180 rate, and the pulsing of contact 160 of that relay provides for the picking up of the relays 13H and 13D in a manner comparable to that heretofore described in detail for the picking up of the relays 9H and 9D. With relays 13H and 13D picked up, the signal 13 is cleared upon the closing of a circuit for the green lamp 13G of that signal extending from (+), including front contact 161 of relay 13H, front contact 162 of relay 13D, and lamp 13G, to (-).

In accordance with the pulsing of contact 163 of the neutral code following relay 13TB at a 180 rate, the relay CEX⁵ is energized during each "on" period of the driven code received for the transmission of a (+) impulse during each "off" period of the driven code. Under such conditions the relay CEX⁵ is picked up during each "on" period of the driven code received upon the closing of front contact 163 of relay 13TB for the energization of a circuit extending from (+), including front contact 163 of relay 13TB, front contact 164 of relay 14D, and lower winding of

relay CEX⁵, to (-). In accordance with the picking up of relay CEX⁵, the closing of front contact 165 conditions the circuit for the inverse code transmitter 13CP so that such relay will be picked up upon the opening of front contact 166 of relay 13TB in a manner heretofore described in detail with respect to the control of relay 9CP.

When the inverse code transmitter relay 13CP is picked up during each of the "off" periods of the driven code for the transmission of a 180 inverse code, the track circuit of track section 12-13T is energized with positive polarity by a circuit closed from the positive terminal of track battery 167 including front contact 159 of relay 13CP, lower rail of track section 12-13T, back contact 158 (see Fig. 2E) of relay 12CP, winding of the code following track relay 12TA, and upper rail of track section 12-13T to the negative terminal of track battery 167.

10 The pulsing of contact 168 of relay 12TA upon the reception of a 180 inverse code transmitted through the track section 12-13T causes the picking up of relays 12H and 12D by the energization of circuits comparable to those which 15 have been described in detail with reference to the control of relays 9H and 9D, the circuit for relay 12H including back contact 169 of relay 11S which is the stick relay for the opposing signal for a purpose to be hereinafter pointed out.

20 The pulsing of contact 168 of relay 12TA upon the reception of a 180 inverse code transmitted through the track section 12-13T causes the picking up of relays 12H and 12D by the energization of circuits comparable to those which 25 have been described in detail with reference to the control of relays 9H and 9D, the circuit for relay 12H including back contact 169 of relay 11S which is the stick relay for the opposing signal for a purpose to be hereinafter pointed out.

30 In accordance with the energized condition of the relays 12H and 12D, if the relay 11TP were dropped away to provide for the illumination of the signal 12, a circuit would be closed to cause 35 the energization of the green lamp 12G of signal 12 extending from (+), including back contact 170 of relay 11TP, front contact 171 of relay 12H, front contact 172 of relay 12D, and lamp 12G, to (-).

40 It has therefore been described in detail how the signal indications as illustrated in Fig. 1B are provided in accordance with the presence of the east bound train A in track section 4-5T, assuming the track layout in advance of such 45 train to be clear, rather than to be occupied by the train B as illustrated. To consider the signal indications provided in accordance with further progress of train A through the track layout, it will be assumed that the train A enters 50 track section 6-7T as illustrated in Fig. 1C, but it will also be assumed that the track layout in advance of the train A is clear instead of being occupied by the train B as illustrated.

Upon comparison of Figs. 1B and 1C, it will 55 be noted that the entrance of the train A into the block immediately in the rear of the entering signal 8 changes the driven code transmitted through the track section 8-9T from a 60 code to a code composed of all (-) impulses to cause 60 signal 9 to indicate danger. It is provided, however, that such change in the transmission of code through track section 8-9T does not affect the transmission of the 90 code through the track section 10-11T in the rear of signal 8 for the caution indication of signal 11. Such being the case, the signal indications will remain as they 65 have been described above, except for the conditioning of signal 9 to provide a danger indication.

To consider the circuits that provide such change in coding for track section 8-9T, with reference to Fig. 2A, the entrance of the train A in the track section 6-7T causes the dropping away of the relay 1T (control of relay not shown). 70 The dropping away of relay 1T opens the cir-

cuit which has been described for the application of (+) impulses of the 60 code previously transmitted through track section 8-9T at front contact 43, and changes the polarity of such impulses from (+) to (—) by closing a circuit for the code transmitter relay 8CP during each period when relay CEX is energized extending from (B—), including back contact 173 of relay 9TP, back contact 174 of relay 9S, front contact 44 of relay CEX, winding of relay 8CP, and back contact 45 of relay 8TB, to (CN). The energization of relay 8CP by such polarity causes it to be picked up with its polar contact operated to a right-hand position to cause the transmission of a (—) impulse through the track circuit in place of each (+) impulse as heretofore described in the transmission of a 60 code.

As a result of changing the code transmitted through track section 8-9T to a driven code having all (—) impulses, the polar code receiving relay 9TA (see Fig. 2B) for the right-hand end of the track section 8-9T fails to pulse, and therefore causes the dropping away of the relay 9H to open the circuit for the yellow lamp of signal 9 at front contact 68, and to provide that the red lamp 9R of signal 9 would be illuminated, if the approach lighting contact 67 of track repeater relay 10TP were closed, by a circuit extending from (+), including back contact 67 of relay 10TP, back contact 68 of relay 9H, and lamp 9R, to (—). It will be noted that the reception of the driven code consisting of all (—) characters at the right-hand end of track section 8-9T maintains the relay 9TP energized because such relay is energized in accordance with the pulsing of contact 58 of the neutral code following relay 9TB which follows the code formed of all (—) impulses. This being true, it will be noted that the stepping continues as has been described of the stepping relays for the left-hand end of track section 10-11T to continue the transmission of a 90 code through such track section because such code is selected to be applied by front contact 111 of relay 9TP which is maintained closed. Such contact when closed shunts out, so to speak, the relays 60C² and 60CA² of the stepping relay bank to provide for the transmission of a 90 code.

To consider further progress of an east bound train through the track layout, assuming the track layout in advance of such train to be unoccupied, a condition will be considered in which the train A has entered the track section 8-9T as illustrated in Fig. 1D. The entrance of the train A into the track section 8-9T of course removes the driven code composed of all (—) impulses as illustrated in Fig. 1C for the track section 8-9T, and the removal of such code changes the code transmitted through track section 10-11T from a 90 code to a 60 code. The reception of such code at the right-hand end of the track section maintains the conditioning of signal 11 to display a caution indication, but causes a change to be effected in the transmission of codes through the track section 12-13T in the rear of signal 11 from a 180 code to a 90 code, and thus causes the signal 13 to display a caution rather than a clear indication. Such caution indication is desirable as it will be hereinafter pointed out more specifically in providing protection for trains in case of simultaneous entry into the short stretch of track extending between sidings.

Assuming the train A to have entered the track section 8-9T as illustrated in Fig. 1D, and as-

suming the track layout in advance of the train to be clear, the code following relays 9TA and 9TB (see Fig. 2B) are both inactive for the right-hand end of the track section 8-9T because of the presence of the train, and the track repeater relay 9TP is dropped away because of the contact 50 of relay 9TB becoming inactive.

In accordance with the drop-away of relay 9TP, the code transmitted through track section 10-11T is changed from a 90 to a 60 code upon the shifting of contact 111 (see Fig. 2C) of relay 9TP in the circuits for the relays of the stepping relay bank associated with the left-hand end of such track section.

15 It is therefore provided, during a cycle of operation of the stepping relay bank, that the shifting of contact 103 of oscillator 180CT² to its upper position following the period in which relay 90CA¹ is picked up, causes the picking up of 20 the relay 60C² by the energization of a circuit extending from (+), including front contact 103 of oscillator 180CT², back contact 104 of relay 9D, back contact 105 of relay 9HA, front contact 110 of relay 90CA¹, back contact 111 of relay 9TP, 25 back contact 175 of relay 9S, lower winding of relay 60C², and back contact 106 of relay CEX², to (—). An obvious stick circuit is closed at front contact 176 of relay 60C² to maintain it energized until the code execution relay CEX² is picked up. The picking up of relay 60C² conditions a pick-up circuit for relay 60CA² which is closed upon the shifting of contact 103 of oscillator 180CT² to its lower position, such circuit extending from (+), including back contact 103 of oscillator 180CT², back contact 111 of relay 60C², and lower winding of relay 60CA², to (—). The picking up of that relay closes an obvious stick circuit at front contact 213 to maintain it picked up until the code execution relay CEX² is picked up for the transmission of a (+) impulse.

40 The picking up of relay 60CA² conditions a circuit for the relay CEX² so that such relay can be picked up upon the shifting of contact 103 of oscillator 180CT² to its upper position to close a circuit extending from (+), including front contact 103 of oscillator 180CT², back contact 104 of relay 9D, back contact 105 of relay 9HA, front contact 178 of relay 60CA², and lower winding of relay CEX², to (—). The picking up of that relay closes its stick circuit at front contact 113 in a manner which has been described to cause the relay to remain picked up for the transmission of the (+) impulse while the other stepping relays are being restored in a manner which has been described. It is, therefore, provided that the front contact 116 of relay CEX² is closed for every third impulse transmitted through the track section 10-11T, the first impulse being (—) in accordance with the polarity of energization of relay 10CP upon the picking up of relay 90C², and the second impulse being (—) in accordance with the energization of relay 10CP upon the picking up of relay 60C² by a circuit extending from (B—), including front contact 114 of relay 90C², front contact 115 of relay 90CA², front contact 119 of relay 60C², back contact 181 of relay 60CA², back contact 116 of relay CEX², winding of relay 10CP, and back contact 117 of relay 10TB, to (CN).

45 In accordance with the reception at the right-hand end of track section 10-11T of a 60 rather than a 90 code, the relay 111HA (see Fig. 2D) which is energized by a circuit tuned to the 90 code is dropped away, but the relay 111H is main-

tained energized by the 60 code to condition the signal 11 for the display of a yellow indication as has been described. The restoration of the relay 11HA, however, causes the code transmitted through track section 12-13T for the control of signal 13 to be changed from a 180 to a 90 code in accordance with the opening of front contact 151 of relay 11HA and the closing of back contact 182 of that relay in the circuits for the stepping relay bank for the left-hand end of that track section.

It is therefore provided that, following a period in which the stepping relays for the left-hand end of track section 12-13T are momentarily deenergized, the shifting of contact 150 (see Fig. 2E) of the oscillator 180CT⁴ to its upper position causes the picking up of the relay 90C⁴ by the energization of a circuit extending from (+), including a front contact 150 of oscillator 180CT⁴, back contact 183 of relay 11D, back contact 182 of relay 11HA, lower winding of relay 90C⁴, and back contact 184 of relay CEX⁴, to (-). The picking up of that relay conditions a pick-up circuit for relay 90CA⁴ so that the shifting of contact 150 to its lower position will cause the picking up of such relay by the energization of a circuit extending from (+), including back contact 150 of relay 180CT⁴, front contact 185 of relay 90C⁴, and lower winding of relay 90CA⁴, to (-). The relays 90C⁴ and 90CA⁴ are both maintained picked up by stick circuits comparable to those which have been described with reference to other stepping relay banks until after the relay CEX⁴ has been picked up. Relay CEX⁴ is picked up when contact 150 of oscillator 180CT⁴ again shifts to its upper position upon the closing of a pick-up circuit extending from (+), including front contact 180CT⁴, back contact 183 of relay 11D, back contact 182 of relay 11HA, front contact 186 of relay 90CA⁴, and lower winding of relay CEX⁴, to (-). A stick circuit is closed at front contact 181 of relay CEX⁴ to maintain it picked up during the restoration of the relays 90C⁴ and 90CA⁴ in a manner similar to that which has been described with reference to the control of other stepping relay banks.

In accordance with the stepping of the relay bank for the left-hand end of track section 12-13T as it has been described, it is provided that every other impulse transmitted through the track circuit is of negative polarity in accordance with the energization of the driven code transmitter relay 12CP during every other impulse by a circuit extending from (B-), including front contact 188 of relay 90C⁴, back contact 189 of relay 90CA⁴, back contact 154 of relay CEX⁴, winding of relay 12CP, and back contact 155 of relay 12TA, to (CN).

In accordance with the reception of a 90 code at signal 13 (see Fig. 2F), the relay 13H is maintained energized, but the relay 13D is dropped away, because of the shifting of the code from a 180 to a 90 rate. It is therefore provided that, in accordance with the dropping away of relay 13D, the green lamp 13G of signal 13 is extinguished by the opening of front contact 162, and the yellow lamp 13Y of that signal is illuminated by the energization of a circuit closed from (+), including front contact 161 of relay 13H, back contact 162 of relay 13D, and lamp 13Y, to (-).

It is therefore provided that, upon entrance of a train into a siding section such as the section 8-9T, for example, the opposing leaving signal for the next siding, such, for example, as signal 13, is put to caution to warn any opposing

train that may be approaching such signal that there is an opposing train at the other end of the stretch of single track between the two sidings involved. It is further provided, as will be hereinafter described with reference to the passage of a west bound train, that protective indications are provided in a similar manner for the opposite direction of traffic.

The approach of signal 8 by an east bound train causes the picking up of a stick relay 8S for signal 8 in order to cause the transmission, after the train has passed out of track section 6-7T as illustrated in Fig. 1D, of a 90 inverse code through the track section 6-7T for the control of signal 6. The transmission of such code through the track section 6-7T causes the signal 6 to display a caution indication, and, inasmuch as the code is at a 90 rate, it is provided that a 180 inverse code is transmitted through the track section 4-5T to cause the clearing of signal 4 as compared to the caution indication such signal 4 would display if the train A were proceeding in the opposite direction. Inasmuch as the circuits by which such code transmission is effected are not shown, a consideration will be here made as to the control of the stick relay 8S used in selecting the controls to be transmitted through the track section 6-7T, and the manner in which such controls can be transmitted will be apparent hereinafter upon considering the transmission of an inverse code through the comparable track section 12-13T after an each bound train has left such track section and entered the siding section 14-15T.

35. The stick relay 8S is picked up upon the entrance of the train A into track section 6-7T by the energization of a circuit extending from (+), including normally closed contact 200 of the switch circuit controller for the track switch 40. at the left-hand end of passing siding 24, back contact 201 of relay 7S, back contact 202 of relay 7TP, front contact 203 of relay 8TP, and winding of relay 8S, to (-). The relay 8S is sufficiently slow acting to be maintained picked up during the shifting of the contact 203 of relay 8TP upon the entrance of the east bound train into track section 8-9T for the closing of a stick circuit extending from (+), including normally closed contact 200 of the switch circuit controller for the track switch at the left-hand end of track siding 24, back contact 201 of relay 7S, front contact 204 of relay 8S, back contact 203 of relay 8TP, and winding of relay 8S, to (-). Such stick circuit remains closed until the train A leaves the track section 8-9T to allow for the picking up of relay 8TP to open the stick circuit just described at back contact 203.

Under assumed operating conditions in which 60. an east bound train A is occupying track section 8-9T with the track layout in advance of the train unoccupied, the leaving signal 10 displays a clear indication in accordance with the reception of a 180 inverse code as heretofore described. When the train A accepts the signal 10 and enters track section 10-11T, the relays 10H and 10D are of course dropped away to cause the green lamp 10G of signal 10 to be extinguished by opening the circuit for such lamp at front contacts 138 and 139. The closing of back contact 138 of relay 10H closes an obvious circuit to cause the illumination of the red lamp 10R of signal 10.

70. Upon the dropping away of the relay 10TP 75. 10R, the red lamp 10R is extinguished by the opening of the circuit for such lamp at front contacts 138 and 139. The closing of back contact 138 of relay 10H closes an obvious circuit to cause the illumination of the red lamp 10R of signal 10.

due to the presence of the train in track section 10-11T, the stick relay 10S for signal 10 is picked up by the energization of a circuit extending from (+), including front contact 205 of relay 10HP, back contact 206 of relay 10TP, and winding of relay 10S, to (-). Such pick-up circuit is only momentarily closed because the relay 10H is dropped away when the train enters the track section 10-11T, and the dropping away of that relay opens on obvious circuit at front contact 207 for the slow acting repeater relay 10HP which is sufficiently slow acting to provide for the picking up of the stick relay 10S. Prior to the opening of the pick-up circuit for the stick relay 10S, a stick circuit is closed for such relay extending from (+), including back contact 207 of relay 10H, front contact 208 of relay 10S, and winding of relay 10S, to (-).

The picking up of the relay 10S provides a means for selecting a code for transmission through the track section 8-9T for the control of signal 8 which, at such signal location, defines the direction of the passage of the train A so as to provide less restrictive signal indications for a following train than would be provided if the train A were proceeding in the opposite direction through the track section 10-11T. It is therefore provided, that when the track section 8-9T becomes unoccupied in the rear of the east bound train A, the code following track relays 9TA and 9TB (see Fig. 2B) at the right-hand end of siding 24 become active to follow a 180 driven code transmitted from the opposite end of the track section in a manner which has been described, it being assumed that the track layout is unoccupied in the rear of train A. The reception of such 180 driven code at the right-hand end of the siding 24 provides for the clearing of signal 9 in a manner which has been described to complete the restoration to normal of the conditions of that track section for the parts of the system affected by the transmission of a driven code.

Restoration to normal of the transmission of an inverse code through track section 8-9T, however, is not effected as the stick relay 10S has been picked up, and the track repeater relay 10TP is dropped away because of the presence of a train in the track section 10-11T. It is therefore provided under such conditions that a 90 inverse code is transmitted through the track section 8-9T because each cycle of operation of the stepping relay bank at the right-hand end of track section 8-9T includes successively the energization of the relays 90C¹, 90CA¹ and CEX¹.

More specifically, assuming the stepping relays to be momentarily deenergized at the end of a cycle of operation during an "off" period of the driven code received, the shifting of contact 58 (see Fig. 2B) of relay 9TB to its upper position upon the reception of the next "on" period of the driven code causes the picking up of the relay 90C¹ (in accordance with the deenergized condition of the relay 10H) by the energization of a circuit extending from (+), including front contact 58 of relay 9TB, back contact 59 of relay 10H, lower winding of relay 90C¹, and back contact 209 of relay CEX¹, to (-). The picking up of that relay conditions a pick-up circuit for the relay 90CA¹ so that such relay is picked up during the next "off" period of the driven code by the energization of a circuit extending from (+), including back contact 58 of relay 9TB, front

contact 210 of relay 90C¹, and lower winding of relay 90CA¹, to (-).

With the stick relay 10S picked up, a circuit is closed upon the shifting of contact 58 to its upper position to cause the picking up of relay CEX¹, extending from (+), including front contact 58 of relay 9TB, back contact 59 of relay 10H, front contact 211 of relay 90CA¹, front contact 212 of relay 10S, and lower winding of relay CEX¹, to (-).

In accordance with the stepping of the relays 90C¹, 90CA¹ and CEX¹ as has been described, it is provided that a 90 inverse code is transmitted through the track section 8-9T, such code being made up of (+) impulses transmitted during the "off" periods of the driven code received at that end of the track section. Inasmuch as the driven code received is at a 180 rate, the composition of the inverse code is such as to provide that each of the (+) impulses of the inverse code is spaced from the next by a single blank period. Such spacing of the impulses is effected because the transmission of each impulse is dependent upon the picking up of the code execution relay CEX¹ to close front contact 60 for conditioning the inverse code transmitter relay 9CP so that it will be picked up upon the opening of front contact 61 of the code following relay 9TB. Relay CEX¹, as has just been described, is pulsed at a 90 rate.

Upon receiving the 90 inverse code at the left-hand end of the passing siding 24, the contact 65 (see Fig. 2A) of relay 8TA is pulsed at a 90 rate, and the pulsing of such relay causes the picking up of relay 8H in accordance with the energization of a circuit similar to that described for the energization of relay 9H. The pulsing of contact 65 of relay 8TA also causes the picking up of relay 8HA because the circuit for such relay is tuned to a 90 rate. It is therefore provided that, if the approach lighting contact 86 of relay 7TP were closed the yellow lamp of signal 8 would be illuminated for the display of a caution indication by the energization of a circuit extending from (+), including back contact 86 of relay 7TP, front contact 87 of relay 8H, back contact 88 of relay 8D, and the yellow lamp 8Y of signal 8, to (-).

In accordance with the energization of relay 8HA upon the reception of a 90 inverse code, it is provided that a 180 inverse code is transmitted through the track section 6-7T in a manner similar to that to be hereinafter described when considering passage of the east bound train beyond signal 14.

In accordance with the general principles of absolute permissive block signaling systems, the entrance of an east bound train into track section 10-11T causes the signals 11 and 13 to be conditioned to display stop indications. The relay 11H (see Fig. 2D) is dropped away in accordance with the presence of the train in track section 10-11T because the pulsing ceases of the contact 122, and the dropping away of that relay opens the circuit which has been described for the yellow lamp 11Y of signal 11 at front contact 135 and conditions a circuit for the red lamp 11R which would be closed if the approach lighting contact 134 of the approach repeater relay 12APP were closed, extending from (+), including front contact 134 of relay 12APP, back contact 135 of relay 11H, and lamp 11R, to (-).

In accordance with the deenergized condition of relay 11H and the opposing stick relay 11S, it is provided that a carrier code made up of all

(-) impulses is applied at the left-hand end of track section 12-13T for transmission to the left-hand end of the siding 25.

The stepping relay bank at the left-hand end of track section 12-13T (see Fig. 2E) is operative during the transmission of a driven code having all (-) impulses in the same manner that has been described for the transmission of a 90 code through that track section in accordance with the deenergized condition of the relays 11D and 11HA, and the (-) impulses are applied to the track circuit 12-13T in the same manner that has been described, except that a (-) impulse is transmitted instead of a (+) impulse each time the code execution relay CEX⁴ is picked up. That is, when the relay CEX⁴ is picked up for the transmission of every other "on" period of the driven code a circuit is closed for the negative energization of the code transmitter relay 12CP extending from (B-) including back contact 215 of relay 11S, back contact 153 of relay 11H, front contact 154 of relay CEX⁴, winding of relay 12CP, and back contact 155 of relay 12TA, to (CN). The picking up of relay 12CP due to such energization causes its polar contact 157 to be in a right-hand position to effect the transmission of a (-) impulse by the energization of a track circuit for track section 12-13T that has been described.

At signal 13, in accordance with the reception of a code composed of all (-) impulses, the polar code following track relay 13TA (see Fig. 2F) ceases to be active, and the relay 13H is dropped away because of the inactivity of contact 160. The dropping away of that relay causes the extinguishing of the yellow lamp 13Y of signal 13 by the opening of front contact 161, and causes the illumination of the red lamp 13R of signal 13 upon the closing of an obvious circuit at back contact 161.

The driven code received at signal 13, however, composed of all (-) impulses, causes the pulsing of the contacts of the neutral code following track relay 13TB, and therefore causes the operation of the stepping relays of the inverse code transmitter for the right-hand end of track section 12-13T to effect the transmission of a 180 inverse code for the clearing of signal 12 in a manner which has been described. Inasmuch as the east bound train is assumed to occupy track section 10-11T, the approach lighting is effective to cause the illumination of the green lamp of signal 12 in accordance with the deenergized condition of the track repeater relay 11TP (see Fig. 2E) to close back contact 170.

The reception of the driven code composed of all (-) characters at the right-hand end of track section 12-13T causes the relay 13TP (see Fig. 2F) to remain picked up in accordance with the pulsing of contact 216, and the energized condition of such relay, with the relay 13H deenergized, provides for the transmission through the track section 14-15T of a 60 code in a manner similar to that which has been heretofore described under similar traffic conditions with reference to the approach of an east bound train to the siding 24.

In accordance with the trackway having been assumed to be clear in the rear of the train occupying track section 10-11T, the energized condition of relay 9D (see Fig. 2B) conditions the stepping relay bank at the left-hand end of track section 10-11T (see Fig. 2C) upon the closing of front contact 194 to provide for the energization of the code execution relay CEX² each time

the front contact 103 of oscillator 180CT² is closed. Thus, the closing of front contact 116 of relay CEX² at a 180 rate causes the application of a 180 driven code to the track section 10-11T in the rear of the east bound train occupying such track section in order to provide for proper restoration upon passage of the train into track section 12-13T.

The stick relay 12S (see Fig. 2E) for signal 12 is picked up upon the approach of such signal by an east bound train in accordance with the energization of a circuit extending from (+), including back contact 217 of relay 11TP, front contact 218 of relay 12H, and winding of relay 12S, to (-). The dropping away of relay 12H upon the shunting of its track section 12-13T when the east bound train passes signal 12, closes a stick circuit for relay 12S extending from (+), including front contact 219 of relay 12S, back contact 218 of relay 12H, and winding of relay 12S, to (-).

Assuming the east bound train to have left the track section 10-11T, the pulsing of contact 122 (see Fig. 2D) of relay 11TA is again effected at a 180 rate to cause the picking up of the relays 11H and 11D, but the picking up of relay 11H is delayed because of the inclusion in its circuit of back contact 123 of the stick relay 12S which is picked up at that time. The inclusion of back contact 123 of relay 12S in the circuit for relay 11H provides that the signal 11 remains at stop to restrict the reversal of direction of the train occupying track section 12-13T in accordance with the general principles of absolute permissive block signaling systems. The signal 11 therefore is not conditioned to be cleared until the single stretch of track extending between the two sidings involved is entirely unoccupied.

In accordance with the deenergized condition of the relays 12H and 12D (see Fig. 2E) due to the presence of the east bound train in track section 12-13T, the green lamp 12G of signal 12 is extinguished by the opening of front contact 172, and the red lamp 12R of signal 12 is illuminated when approach lighting is effective for such signal 12 by the energization of an obvious circuit selected by the dropped away condition of the relay 12H at back contact 171.

The transmission of a 90 inverse code becomes effective through the track section 10-11T for the control of signal 10 in accordance with the energized condition of the stick relay 12S which has been picked up. Thus, the stepping is effective to cause the energization of the code execution relay CEX³ (see Fig. 2D) for the transmission of an impulse during every other "off" period of the 180 driven code received in accordance with the deenergized condition of the relays 12HA and 12D. It is therefore provided that the closing of front contact 128 of relay 11TB following an "off" period in which the stepping relays are all deenergized causes the relay 90C³ to be picked up by the energization of a circuit extending from (+), including front contact 129 of relay 11TB, back contact 129 of relay 12D, back contact 220 of relay 12HA, lower winding of relay 90C³, and back contact 221 of relay CEX³, to (-). During the following "off" period of the driven code received, the relay 90CA³ is picked up by the energization of a circuit extending from (+), including back contact 128 of relay 11TB, front contact 222 of relay 90C³, and lower winding of relay 90CA³, to (-). The picking up of relay 90CA³ conditions a pick-up circuit for the relay CEX³ so that such relay is picked up upon the

picking up of relay 11TB during the following "on" period of the driven code received, by the energization of a circuit extending from (+), including front contact 128 of relay 11TB, back contact 129 of relay 12D, back contact 220 of relay 12HA, front contact 223 of relay 99CA³, and lower winding of relay CEX³, to (-). Stick circuits are provided for the stepping relays in a manner similar to that which has been described in detail with reference to similar stepping relay banks in order to provide for the proper restoration of the relays for the completion of their cycle of operation. The front contact 224 of relay CEX³, is closed as a result of the reception of every other impulse of the 180 driven code to cause the energization at a 90 rate of the inverse code transmitter relay 11CP. In accordance with the pulsing of the relay 11CP, (+) impulses are transmitted through the track section 10-11T by the energization of a circuit that has been described, except that such circuit is closed by front contact 225 of the stick relay 12S instead of by front contact 132 of relay 12H.

In accordance with the reception at the left-hand end of the track section 10-11T of a 90 inverse code, the pulsing of contact 137 (see Fig. 2C) of relay 10TA at a 90 rate causes the picking up of the relay 10H which extinguishes the red lamp 10R of signal 10 by the opening of back contact 138 and closes a circuit for the yellow lamp 10Y of that signal extending from (+), including front contact 138 of relay 10H, back contact 139 of relay 10D, and lamp 10Y, to (-). The picking up of relay 10H also causes the dropping away of the stick relay 10S by opening its stick circuit at back contact 207.

Upon the picking up of relay 10H, conditions are restored to normal for the right-hand end of track section 8-9T to cause the stepping of the relay bank to be effective for the transmission of a 180 inverse code for the control of signal 8 to condition such signal so that the green lamp 8G can be illuminated in accordance with the approach of a train. The conditions which have been described as normal have thus been restored for the track section 8-9T and for the signals 8 and 9 governing passage of trains in both directions through such section.

It will be noted that the signal location at the left-hand end of siding 25 (see Fig. 2F) is similar to the signal location shown in Fig. 2A for the left-hand end of siding 24, and it is therefore to be understood that the apparatus and circuits associated with the left-hand end of the track section 14-15T and the signal 14 are similar to the apparatus and circuits shown in detail in Fig. 2A associated with the left-hand end of track section 8-9T and the control of the signal 8. It will therefore be readily apparent that the presence of a west bound train in track section 12-13T (see Fig. 2F) causes the picking up of the stick relay 14S (circuit not shown) by a circuit similar to that described in detail for the stick relay 8S associated with signal 8, and upon the passage of the east bound train past the signal 14, the stick relay 14S is maintained picked up by the energization of a stick circuit similar to that shown and described for the relay 8S.

To consider further progress of an east bound train through the track layout, assume that the train leaves track section 12-13T, and that the track layout in the rear of the train is unoccupied. Under such conditions the relay 14TP for the lefthand end of track section 14-15T is dropped away in a manner similar to the deener-

gization of the relay 8TP (see Fig. 2A) under comparable traffic conditions at the left-hand end of the siding 24, and such relay being de-energized, with the stick relay 14S picked up, 5 selects a 90 inverse code for transmission back through the track section 12-13T in the rear of the train to condition the signal 12 for a caution indication.

As soon as the east bound train has left the 10 track section 12-13T, the code following relays 13TB and 13TA are operative in response to a 180 driven code being transmitted from the left-hand end of the track section 12-13T. Such driven code is transmitted at that time in accordance 15 with the closing of front contact 163 (see Fig. 2E) of relay 11D to provide that the code execution relay CEX⁴ is picked up each time the front contact 150 of oscillator 180CT⁴ is closed, and the picking up of that relay causes the transmission 20 of a (+) impulse in a manner which has been described. The reception of a 180 code at signal 13 (see Fig. 2F) causes the pulsing of contact 160 of relay 13TA to effect the energization of relays 13D and 13H, the relay 13D being tuned to 25 the 180 rate received. Thus, the picking up of relay 13H causes the extinguishing of the red lamp 13R of signal 13 by the opening of back contact 161, and a circuit is closed for the green lamp 13G of signal 13 extending from (+), including front contact 161 of relay 13H, front contact 162 of relay 13D, and lamp 13G of signal 13, to (-).

In accordance with the pulsing of contact 163 of the neutral code following relay 13TB, the inverse transmitter relay bank for the right-hand end of track section 12-13T becomes active to transmit a 90 inverse code through the track section 12-13T for the control of signal 12. Such 30 90 code is selected in accordance with the dropped away condition of the relay 14TP and the energized condition of the stick relay 14S, the relay 14S being effective in the sequence of operation of the stepping relay bank to effectively shunt the relays 90C⁵ and 90CA⁵ out of the stepping bank operation by closing a circuit to cause the picking up of the code execution relay CEX⁵ during the "on" period of the driven code received following the "off" period in which the relay 90CA⁵ is picked up. More specifically, assuming 35 the stepping relays all to be dropped away during an "off" period of the driven code received, the shifting of contact 163 to an upper position upon the reception of the next impulse of the driven code causes the picking up of the relay 90C⁵ by the energization of a circuit extending from (+), including front contact 163 of relay 13TB, back contact 164 of relay 14D, back contact 230 of relay 14HA, lower winding of relay 90C⁵, and back contact 231 of relay CEX⁵, to (-). 40 During the following "off" period of the driven code the relay 90CA⁵ is picked up by the energization of a circuit extending from (+), including back contact 163 of relay 13TB, front contact 232 of relay 90C⁵, and lower winding of relay 90CA⁵, to (-). During the following "on" period of the driven code received, the execution relay CEX⁵ is picked up by the energization of a circuit extending from (+), including front contact 163 of relay 13TB, back contact 164 of relay 14D, back contact 230 of relay 14HA, front contact 233 of relay 90CA⁵, back contact 234 of relay 14TP, front contact 235 of relay 14S, and lower winding of relay CEX⁵, to (-). Stick circuits 45 are of course provided for the stepping relays in a manner which has been described for the step-

ping relay bank at the left-hand end of track section 8-9T to provide properly for their restoration at the end of a cycle of operation of the stepping relay bank. In accordance with the closing of front contact 165 each time the relay CEX⁵ is picked up, the inverse code transmitter relay 13CP is picked up during every other "off" period of the 180 driven code received to cause the transmission for the control of signal 12 of a 90 inverse code.

The reception of a 90 code at signal 12 causes the code following relay 12TA (see Fig. 2E) to become active to effect the picking up of the relay 12TP in an obvious manner upon the pulsing of contact 155. The pulsing of contact 168 of relay 12TA at a 90 rate causes the picking up of the relays 12H and 12HA by the energization of circuits similar to those described in detail for the energization respectively of relays 9H and 11HA, the circuit for relay 12H differing from the circuit described for relay 9H in the inclusion of back contact 169 of the stick relay 11S which is of course dropped away at that time, because such stick relay is picked up only for west bound traffic.

In accordance with the picking up of relay 12H, a circuit is conditioned (depending upon the closing of the approach lighting contact 170) for signal 12 for the illumination of the yellow lamp 12Y for a caution indication, extending from (+), including back contact 170 of relay 11TP, front contact 171 of relay 12H, back contact 172 of relay 12D, and lamp 12Y, to (-).

The picking up of relay 12HA selects a 180 inverse code for transmission through the track section 10-11T for the clearing of signal 10. The transmission of such code is effected in a manner which has been described, except that the circuit for relay CEX³ (see Fig. 2D) is closed at front contact 236 of relay 12HA instead of front contact 129 of relay 12D, as was the case under the conditions which have been heretofore described. It will be noted that the energization of the relay 12HA prevents the energization of the relay 90C³ by opening the circuit for that relay at back contact 220. Thus at the left-hand end of track section 10-11T, the relay 10TA (see Fig. 2C) becomes active to pulse contact 137 at a 180 rate, and therefore causes the picking up of relay 10D to extinguish the yellow lamp 10Y of signal 10 by opening back contact 139, and to cause the illumination of the green lamp 10G of signal 10 by the energization of a circuit which has been described.

As the east bound train proceeds through the track layout and leaves the track section 14-15T (see Fig. 1A), the presence of the train in track section 16-17T causes the transmission in the rear of the train of a 90 inverse code in a manner identical to that which has been described in detail with reference to the transmission of a 90 inverse code through track section 8-9T upon assuming the passage of an east bound train into track section 10-11T. In other words, the track layout being made up of track portions similar to the track portion illustrated in detail in Figs. 2A, 2B, 2C, 2D, 2E and 2F, it is believed to be readily apparent that the consideration of further passage of an east bound train would only involve the repetition of detail description for similar traffic conditions in the track portion which has been illustrated and described in detail. It may be pointed out, however, that the east bound train upon leaving track section 14-15T allows the transmission of a 90 code through such track

section for the control of signal 14 to condition such signal to display a caution indication, and upon the reception of the 90 code for the control of signal 14, the relay 14HA (see Fig. 2F) is picked up. The picking up of such relay causes the transmission through the track section 12-13T of a 180 inverse code. Such 180 inverse code is transmitted through track section 12-13T in a manner which has been described except that the relay CEX⁵ is picked up in accordance with the closing of front contact 231 of relay 14HA instead of in accordance with a front contact 164 of relay 14D as heretofore described. The relays 90C⁵ and 90CA⁵ become inactive in accordance with the picking up of relay 14HA because of the opening of the circuit for relay 90C⁵ at back contact 230. In accordance with the transmission of a 180 inverse code through track section 12-13T the signal 12 is conditioned to display a clear indication in a manner which has been heretofore described.

Passage of a west bound train.—Although there is some difference in the characteristics of the circuits employed upon passage of a west bound train from the character of circuits employed upon the passage of an east bound train, the general mode of operation of the system is the same for both directions of traffic. Similar codes are transmitted under similar traffic conditions, and therefore the description as has been set forth in detail for passage of an east bound train can be applied to similar traffic conditions for a west bound train except that the type of codes employed, namely, driven and inverse codes, are opposite from the codes heretofore considered with reference to similar traffic conditions for east bound traffic. This is true because driven codes are always transmitted through the track circuits to the right and inverse codes are always transmitted through the track circuits to the left, irrespective of the direction of traffic through the track layout. Thus, the codes received for the clearing of signals in advance of a west bound train are driven codes and the codes transmitted for the control of opposing signals are inverse codes, while under the conditions which have been described, the inverse codes are used for clearing signals in advance of an east bound train, and driven codes are transmitted for the control of opposing signals. Aside from this difference it can be said that the mode of operation of the system for west bound traffic is the same as the mode of operation for east bound traffic. The rate of the codes used is similar for the various traffic conditions for both directions of traffic, but the nature of the codes used (driven or inverse) varies for the opposite directions of traffic. Such being the case, it is believed unnecessary for those skilled in the art to describe in detail all of the circuits concerned in the passage of west bound trains, but a consideration will be given to the general mode of operation upon passage of a west bound train, and certain circuits differing from those which have been described will be considered in detail.

Before considering the passage of a west bound train it may be expedient to point out similarities in the circuits provided for governing both directions of traffic. It will be noted that the conditions involving the control of the signals 7 and 8 (see Fig. 2A), and the codes transmitted through the adjoining track circuits for various purposes can be compared to the conditions involving the control of the signals 9 and 10 (see

Fig. 2B) and the codes transmitted through the adjacent track circuits. The signals 8 and 9 are both entering signals for the siding section and therefore are similar in that respect, and the signals 7 and 10 are both leaving signals for the siding section. Thus, inasmuch as the system provided by the present invention is symmetrical in the use of codes for both directions of traffic, the indications of the leaving signals 7 and 10 are governed in accordance with the reception of similar codes, and the same condition exists with respect to the entering signals 8 and 9.

Inasmuch as the codes received for the control of signal 8 are similar to the codes received for the control of signal 9, it is provided that the decoding of the codes received at each of such signals is provided in the same manner to cause the selective energization of the relays H, HA and D which are used for decoding purposes. Likewise, the stick relay S provided for each of such signals has a control identical to the stick relay S for the entering signal at the opposite end of the siding.

Although the left-hand end of the siding section 8-9T has a driven code transmitter while the right-hand end of that siding section has an inverse code transmitter, the control of the stepping relay banks for both transmitters are similar except in that the driven code transmitter relay bank is operated from an oscillator, while the inverse transmitter relay bank is operated from a neutral code following relay TB. To compare the circuits for the two relay banks more specifically, it will be noted that in each case the front contact of an H relay for the opposing signal at that location selects when closed the transmission of a 180 code. If such H relay is dropped away in either case, a contact of the stick relay for the opposing signal at that location selects as to whether a 90 or a 60 code is to be transmitted. If such stick relay is picked up, it is selected that a 90 code is to be transmitted, and if such stick relay is dropped away, it is selected that a 60 code is transmitted providing that the relay TP for the adjoining track section is energized. Such selection by the relay TP for the adjacent track section is provided directly in the track circuit. If the relays H, S and TP for selecting code transmission at either end of the track section are all dropped away, a code composed of all (—) impulses is selected for transmission.

A comparison can also be drawn between the control of signals 10 (see Fig. 2C) and 13 (see Fig. 2F) as they are both leaving signals, and between the code transmitters and receivers associated with the entering end of the blocks in advance of such signals. Here again it will be noted that the codes employed for the control of the signals 10 and 13 are similar, and therefore such codes are decoded by similar apparatus, and the selection of the codes for transmission in advance of each of such signals is identical to the code selecting means provided for the opposing leaving signal.

It will be noted that the selection of the codes for transmission in advance of either signal 10 or signal 13 is effected in a manner slightly different from that provided for the transmission of codes through the siding section, but it is believed to be readily apparent from the detailed description as it has been set forth why these different selections are provided. It will be noted, for example, that the closing of a front contact of either relay 9D or relay 9HA (see Fig. 2C) provides for

the transmission of a 180 code through track section 10-11T, and that the transmission of a 90 code is dependent upon the deenergized condition of relay 9D and 9HA together with the energized condition of either relay 9TP or relay 9S. The energization of relay 9S is an indication of passage of a west bound train and thus selects the transmission of a 90 code for a following train. The energization of the relay 9TP of course indicates that the siding section is unoccupied, and therefore less restrictive indications are required than would be the case if such siding section were occupied by an east bound train. The 60 code is selected for transmission if relays 9D, 9HA, 9TP and 9S are all dropped away. Such transmission causes the leaving signal 13 (see Fig. 2F) at the siding 25 to display a caution indication. It will be noted that a similar circuit organization is provided at signal 13 for the selection of the various codes for transmission through the track section 12-13T.

To continue the comparison further of the control of opposing signals, the intermediate signals 11 and 12 (see Figs. 2D and 2E) are similar to each other in the signal indications they display for their respective directions of traffic upon receiving similar codes. The code transmission and reception apparatus associated with each of such signals for the block in advance thereof is similar in its decoding and stepping relay bank operation to like apparatus provided for the opposing intermediate signal.

It will be noted that for each track section terminating at the double intermediate location, that the decoding apparatus is arranged to receive 180 and 90 codes as distinctive from a 60 code, while the stepping relay bank of the code transmitter is arranged for the transmission of only 90 and 180 codes aside from the transmission of codes having all (—) characters. This obviously is arranged in accordance with the number of different controls required to be communicated to and from the intermediate signals 11 and 12. It is believed to be apparent to those skilled in the art that the stepping relay banks and decoding apparatus are both readily adaptable in accordance with the requirements of practice to the number of distinctive codes required to be transmitted or received at a given signal location.

With the above comparisons in mind and with reference to Figs. 1B, 1C and 1D, the passage of a west bound train will be considered in which the train B is initially occupying the track section 18-19T as illustrated in Fig. 1B. The occupancy of such track section causes the transmission of an inverse code as illustrated having all (—) characters through the track section 16-17T, and the reception of such code at signal 16 causes that signal to be maintained at stop, but the track repeater relay TP at such signal location for the track section 16-17T is maintained energized and thus selects a 60 code for transmission through the track section 14-15T in a manner similar to that described upon considering the approach of an east bound train to the left-hand end of siding section 24.

Upon the reception of a 60 code at signal 14, such signal is conditioned to display a caution indication, and the energized condition of the relay 14TP upon receiving the 60 code selects a 90 inverse code by the closing of front contact 234 (see Fig. 2F) for transmission through the track section 12-13T to condition the signal 12 for

the display of a caution indication in a manner which has been described. The reception of the 90 code at signal 12 picks up the relay 12HA (see Fig. 2E), and the energization of such relay selects by closing front contact 236 (see Fig. 2D) a 180 code for transmission through the track section 10-11T for the clearing of signal 10.

To consider further progress of a west bound train, with reference to Fig. 1C, assume the train B to have entered the track section 16-17T, and also assume the trackway in advance of the train to be unoccupied. Under such conditions the 60 code previously transmitted through track section 14-15T is changed to a code having all (—) impulses, and such change causes the dropping away of the relay 14H to cause the signal 14 to be conditioned for the display of a red indication. The code received at signal 14, however, maintains the track repeater relay 14TP picked up, and thus maintains for transmission the 90 inverse code through the track section 12-13T for the caution indication of signal 12. It is therefore provided under such conditions that the relay 12HA at signal 12 is maintained energized, and the energization of such relay maintains the transmission of a 180 inverse code through the track section 10-11T for the clearing of signal 10. The transmission of a 180 driven code through each of the track sections in advance of the train is of course maintained in accordance with the normal conditions of the system.

With reference to Fig. 1D, upon entrance of the train B into track section 14-15T (assuming the trackway in advance of the train to be unoccupied) the track repeater relay 14TP for the left-hand end of such track section is dropped away, and the dropping away of such relay causes the relays 60C⁵ (see Fig. 2F) and 60CA⁵ to be included in each cycle of operation of the stepping relay bank, and therefore provide for the transmission of a 60 code rather than a 90 code through the track section 12-13T for the control of signal 12. Under such conditions the relay 60C⁵ is picked up during the "on" period of the driven code received at the right-hand end of track section 12-13T, following the "off" period in which the relay 90CA⁵ is picked up, by the energization of a circuit extending from (+), including front contact 163 of relay 13TB, back contact 164 of relay 14D, back contact 230 of relay 14HA, front contact 233 of relay 90CA⁵, back contact 234 of relay 14TP, back contact 235 of relay 14S, lower winding of relay 60C⁵, and back contact 231 of relay CEX⁵, to (—). During the following "off" period of the driven code received, the relay 60CA⁵ is picked up by the energization of a circuit extending from (+), including back contact 163 of relay 13TB, front contact 238 of relay 60CA⁵, and lower winding of relay 60CA⁵, to (—). It is therefore provided that a 60 inverse code is transmitted through the track section 12-13T under the assumed traffic conditions, and the reception of such code at signal 12 conditions such signal for the display of a caution indication as would be the reception of a 90 code, but the relay 12HA (see Fig. 2E) is dropped away, as such relay is energized only upon the reception of a 90 inverse code.

The dropping away of relay 12HA selects for transmission through the track section 10-11T for the control of signal 10, a 90 inverse code instead of the 180 code previously transmitted. Such selection is effected by the opening of front contact 236 (see Fig. 2D) and the closing of back contact 220 of relay 12HA in the circuits for the

5 relays of the stepping relay bank at the right-hand end of track section 10-11T. It is thus provided that all three relays of the stepping relay bank are active to cause the transmission of a 90 code for the control of signal 10 in a manner which has been described. Upon receiving such 10 90 code at signal 10, the relay 10D (see Fig. 2C) is dropped away, and such relay in dropping away opens the circuit at front contact 139 for the 15 green lamp of signal 10 and causes the illumination of the yellow lamp 10Y for such signal upon closing back contact 139. The relay 10H is of course maintained picked up in accordance with the reception of the 90 code, and therefore maintains the transmission of a 180 inverse code through the track section 8-9T to condition signal 8 so that it can be cleared (dependent upon approach lighting).

To consider further progress of the west bound train B, assume that such train accepts the leaving signal 13 and enters the track section 12-13T at a time when the trackway for considerable distance in advance of such train is unoccupied. The presence of the train in such track section of course causes the relays 13H (see Fig. 2F) and 13D to be dropped away to provide for the illumination of the red lamp 13R of signal 13 upon the closing of back contact 161 of relay 13H. The presence of the train also causes the dropping away at the left-hand end of track section 12-13T of the relays 12TP (see Fig. 2E) and 12H to condition the signal 12 for the illumination of the red lamp 12R, dependent upon approach lighting.

35 It is provided in accordance with the presence of the west bound train in track section 12-13T that an inverse code having all (—) impulses is transmitted through the track section 10-11T to cause the dropping away of the relay 10H (see Fig. 2C) at signal 10 for the illumination of the red lamp 10R of such signal, and yet maintain the track repeater relay 10TP for the left-hand end of track section 10-11T energized for maintaining the transmission of a code through the track section 8-9T by the closure of front contact 63 (see Fig. 2B) of such relay in the track circuit of track section 8-9T. The dropping away of the relay 10H, however, with the relay 10S dropped away, changes the code to a 60 in a 40 manner to be hereinafter more specifically considered.

45 To consider more specifically the circuits causing the general mode of operation described above, it will be noted that the inverse code transmitter relay 11CP (see Fig. 2D) is picked up during each "off" period of the driven code received through the track section 10-11T because of the opening at the end of each "on" period of the driven code of a circuit for the primary winding 50 of the transformer 11TFB extending from (+), including back contact 239 of relay 12H, back contact 240 of relay 12S, front contact 241 of relay 11TB, and primary winding of transformer 11TFB, to (—). It is provided that negative polarity is applied to the track circuit of track section 10-11T each time the inverse code transmitter relay 11CP is picked up by the energization of the track circuit extending from the negative terminal of track battery 130, back contact 242 of relay 12S, back contact 132 of relay 12H, front contact 119 of relay 11CP, lower rail of track section 10-11T, back contact 120 of relay 10CP (see Fig. 2C), winding of relay 10TB, winding of relay 10TA, and upper rail of track section 10-11T to the center terminal of the track bat-

tery 130. In accordance with the energization of such circuit, each time the inverse code transmitter relay 11CP is picked up, the neutral code following track relay 10TB follows the code to cause the relay 10TP to be maintained picked up by the pulsing of contact 117, but the relay 10TA does not respond to such code because of the polarity of the impulses applied.

In accordance with the dropping away of relay 10H, with the stick relay 10S for east bound traffic in a deenergized position, it is provided that the relay 60CA¹ (see Fig. 2B) in the stepping relay bank for the right-hand end of track section 8-9T is picked up during the "on" period of the driven code received, following an "off" period in which the relay 60CA¹ is picked up, by the energization of a circuit extending from (+), including front contact 58 of relay 9TB, back contact 59 of relay 10H, front contact 211 of relay 90CA¹, back contact 212 of relay 10S, lower winding of relay 60C¹, and back contact 209 of relay CEX¹, to (-). The relay 60CA¹ is of course picked up during the following "off" period of the driven code received, by the energization of a circuit extending from (+), including back contact 58 of relay 9TB, front contact 243 of relay 60C¹, and lower winding of relay 60CA¹, to (-). It is therefore provided that all of the relays of the stepping relay bank are active during each cycle of operation of such bank to select a 60 code for transmission through the track section 8-9T for the control of signal 8.

Upon the reception of the 60 inverse code at signal 8, such signal is conditioned for the display of a caution indication because the relay 8H is maintained energized, but the relay 8D is dropped away on account of the change in the code transmitted through the track section 8-9T. It is further provided, in accordance with the general principles of the system as they have been described, that the reception of the 60 code at signal 8 causes the transmission of a 90 code through the track section 6-7T in the rear of such signal to cause such signal in the rear to be conditioned to display a caution indication. The reception of a 90 code at such signal, in addition to selecting the caution indication of that signal, selects that a 180 code will be transmitted on through the next track section toward the siding 23 (see Fig. 1A) to cause the clearing of the leaving signal 4 for such siding. Although the circuits providing such mode of operation are not shown in detail, it will be readily apparent to those skilled in the art that such circuits are identical to those shown and described for the control of comparable signals in the stretch of track between the passing sidings 24 and 25.

The stick relay 11S (see Fig. 2D) for signal 11 is picked up when the west bound train is in approach of such signal in accordance with the picking up of the approach repeater relay 12APP, by the energization of a circuit similar to that described with reference to the control of the stick relay 12S (see Fig. 2E) when considering the passage of an east bound train. It will be noted that the neutral approach code following relay 12AP is active when the track section 12-13T is occupied by a train because of the increased flow of current through its winding connected in series with the track battery 156 in the track circuit which is shunted. By varying the characteristics of the relay 12AP, it can be provided that such relay becomes active when

a train is at any given distance in approach of signal 11 in the track section 12-13T. The pulsing of contact 251 of relay 12AP causes the relay 12APP to be picked up in an obvious manner, such relay being sufficiently slow acting to be maintained picked up during the "off" periods. The closing of front contact 134 of relay 12APP (see Fig. 2D) of course provides for approach lighting for signal 11 in an obvious manner:

When the track section 12-13T is unoccupied in the rear of the west bound train, a 90 code is transmitted through such track section in accordance with the energized condition of the stick relay 11S. Thus, the driven code transmitter relay bank for the left-hand end of track section 12-13T (see Fig. 2E) has all of its relays active for the transmission of a 90 code in a manner which has been described, the relay 90C⁴ being picked up every second time that front contact 150 of oscillator 180CT⁴ is closed in accordance with the closed condition of back contacts 183 and 182 of relays 11D and 11HA respectively. The energization of the track circuit with alternately (+) and (-) impulses is effected in a manner which has been described, except that the energization of the track circuit for the transmission of the (+) impulses is effected in accordance with the closed condition of front contact 244 of relay 11S, instead of the front contact 153 of relay 11H which was included in the circuit as it was originally described. The opening of back contact 215 of relay 11S in the circuit for the code transmitter relay 12CP prevents the improper application of (B-) energy to the circuit for relay 12CP.

In accordance with the reception of the 90 code at the right-hand end of track section 12-13T (see Fig. 2F), the red lamp of signal 13 is extinguished upon the picking up of the relay 13H, and the yellow lamp 13Y of such signal is illuminated by the energization of an obvious circuit closed at front contact 161 of relay 13H and at back contact 162 of relay 13D. In accordance with the energization of the relay 13H at the right-hand end of track section 12-13T, it is provided that a 180 code is transmitted back through the adjoining track section 14-15T for the clearing of the next signal in the rear in a manner similar to that illustrated in detail for a similar track circuit in Fig. 2A.

Responsive to the reception of a driven code at the right-hand end of track section 12-13T, the inverse code transmitter becomes active to transmit a code for the control of signal 12 in accordance with the traffic conditions in advance of signal 14. If the track layout is unoccupied for some distance in advance of such signal, the relay 14D is picked up, and the picked up condition of such relay selects a 180 inverse code for transmission through the track section 12-13T. The reception of such code at the left-hand end of track section 12-13T (see Fig. 2E) causes the picking up of the relay 12D, but the signal 12 cannot be cleared because the relay 12H can be picked up only after the restoration of the stick relay 11S, which is energized at that time to close back contact 169.

In accordance with the presence of the west bound track in track section 10-11T, the relay 10TP (see Fig. 2C) at the left-hand end of track section 10-11T, which has been maintained energized upon the reception of a code composed of all (-) characters, is dropped away, and the dropping away of such relay changes the code

transmitted through the track section 8-9T for the control of signal 8 from a 60 code to a code composed of all (—) characters.

The dropped away condition of the relay 10TP provides steady energization to the front contact 61 (see Fig. 2B) of relay 9TB in accordance with the closed condition of back contacts 245 and 246 of relays 10S and 10TP respectively. Obviously, such arrangement provides that the inverse code transmitter relay 9CP will be picked up during each "off" period of the driven code received, in accordance with the pulsing of contact 51 of the relay 9TB, and it will be noted that such operation is effective irrespective of the condition of operation of the stepping relay bank for that end of the track section 8-9T.

Each time the front contact 49 of the inverse code transmitter relay 9CP is closed, negative energization becomes effective for the track circuit of track section 8-9T in accordance with the energization of a circuit extending from the negative terminal of the center tap track battery 62 including back contact 247 of relay 10TP, back contact 248 of relay 10S, front contact 49 of relay 9CP, lower rail of track section 8-9T, back contact 48 (see Fig. 2A) of the code transmitter relay 8CP, winding of relay 8TB, winding of relay 8TA, and upper rail of track section 8-9T to the center terminal of track battery 62.

The reception of an inverse code composed of all (—) characters at the left-hand end of track section 8-9T causes the signal 8 to be conditioned for the energization of a red lamp (dependent upon approach lighting) in accordance with the closing of back contact 87 of relay 8H. The relay 8TP is maintained picked up upon the reception of such code, however, in accordance with the pulsing of contact 45 of the neutral code following relay 8TB, and the picked up condition of such relay selects a 90 inverse code for transmission through the track section 6-7T in a manner identical to that shown for transmission of a 90 inverse code through the track section 12-13T (see Fig. 2F) under similar traffic conditions with respect to the approach of a west bound train to siding 25.

With reference to Fig. 1A, the transmission of a 90 code through the track section 6-7T causes the signal 6 to be conditioned to display a caution indication in a manner similar to that described for the caution indication of signal 12 under similar traffic conditions, and the reception of the 90 code at such signal also conditions the inverse code transmitter for the track section 4-5T to transmit a 180 inverse code for the clearing of signal 4. Such transmission is also effected in a manner identical to similar conditions described in accordance with the control of signal 10.

The presence of the west bound train in track section 10-11T causes the stick relay 9S (see Fig. 2B) to be picked and to close its stick circuit in a manner similar to that which has been described in detail with reference to the control of the stick relay 8S (see Fig. 2A) provided for west bound traffic at the left-hand end of the siding section 8-9T. The picking up of such relay serves the purpose of selecting a 90 driven code for transmission through the track section 10-11T for the control of signal 11, but such code of course cannot be effectively transmitted through the track section 10-11T until such track section becomes unoccupied in the rear of the train. However, when the track section 10-11T does become unoccupied in the rear of

a train, transmission of a 90 driven code becomes effective in a manner which has been described, except that the relays 60C² (see Fig. 2C) and 60CA² of the stepping relay bank for the left-hand end of track section 10-11T are effectively shunted out of the operation of the stepping relay bank in accordance with the closure of front contact 175 of the stick relay 9S, such front contact being effective instead of the front contact 111 of the relay 9TP, as was the case under the conditions heretofore described, for the transmission of a 90 code through that track section.

The reception of a 90 driven code at signal 11 causes the picking up of relays 11H (see Fig. 2D) and 11HA, and causes the signal 11 to be conditioned for the display of a caution indication in a manner which has been described. The picking up of the relay 11HA of course selects a 180 driven code for transmission through the track section 12-13T in accordance with the closure of front contact 151 (see Fig. 2E) in the stepping relay bank circuits for the left-hand end of such track section. The relay 13D (see Fig. 2F) for the control of signal 13 of course responds to the reception of a 180 code at such signal location, and closes front contact 162 to extinguish the yellow lamp 13Y of signal 13 and cause the illumination of the green lamp 13G.

In accordance with the picking up of the relay 11H (see Fig. 2D) at the double intermediate signal location, the opening of back contact 249 in the stick circuit of relay 11S causes the dropping away of that relay, and such relay in dropping away closes back contact 169 (see Fig. 2E) of relay 12H to allow such relay to be picked up. Inasmuch as the relay 12D is picked up at that time, it is provided that the signal 12 is conditioned (dependent upon approach lighting) to display a clear indication.

After the track section 10-11T has become unoccupied in the rear of the west bound train, assuming the trackway to be clear for some distance in the rear of such train, a 180 inverse code is transmitted through the track section 10-11T for the clearing of signal 10. Such 180 inverse code is transmitted from the right-hand end of track section 10-11T in a manner which has been described in accordance with the closed condition of front contact 129 of relay 12D in the circuits for the stepping relay bank for that end of the track section. Assuming the progress of the west bound train to be through the main track section 8-9T, the presence of the train in such track section causes the dropping away of the relay 8TP (see Fig. 2A) for the left-hand end thereof, and such relay in dropping away changes the code transmitted through the adjoining track section 6-7T from a 90 code to a 60 code in a manner similar to an identical condition which has been described for transmission of a 60 code through the track section 12-13T. With reference to Fig. 1A, the signal 6 is maintained at caution under such traffic conditions due to the reception of the 60 inverse code, but the shifting of the inverse code from a 90 to a 60 rate, causes the dropping away of the HA relay for such signal, and the dropping away of that relay changes the inverse code transmitted through the track section 4-5T from a 180 to a 90 code in order that the signal 4 will have its green lamp extinguished and its yellow lamp illuminated for the display of a caution indication. Such mode of operation is of course similar to the mode of operation described under sim-

ilar traffic conditions with respect to the transmission of codes through the track section 10-11T in accordance with the occupancy by a west bound train of the siding track section 14-15T.

Passage of opposing trains.—Having thus described specifically the mode of operation of the system upon passage of a train in each direction, consideration is now given to the meeting of trains at a passing siding. The nature of the system is such that the opposing restrictive signal indications described in detail for each respective direction of traffic are identical to those that would be encountered by an opposing train. Such is the case because the opposing signal indications provided in advance of a train do not have their indications affected or dependent in any way upon the approach of a train governed by such signals (except of course for the approach lighting of certain of the signals). The mode of operation upon the meeting of trains should, therefore, be readily apparent to a person skilled in the art from the description as it has been set forth and upon reference to Figs. 1A, 1B, 1C, 1D and 1E.

It will be noted with reference to Fig. 1D that the leaving signals 10 and 13 for the trains A and B respectively both display caution indications to inform the trainmen of each train that they should be prepared to stop short of the first intermediate signal to be encountered. Upon consideration of the circuits heretofore described for the passage of trains A and B respectively through the track layout, it will be apparent that the opposing signals in advance of each train are governed in the same manner which has been described. Should either or both of the trains illustrated in Fig. 1D enter the stretch of single track between the sidings 24 and 25, the opposing signals governing passage through such stretch of track would obviously display danger and stop indications in accordance with the mode of operation as considered upon passage of each respective train through the track layout. It will be apparent that the entrance of two opposing trains into the same stretch of single track between sidings is an abnormal condition in which the trainmen of one of the trains would have to disobey the train orders, but, nevertheless, safety requires the provision of such conditions if they should occur.

In accordance with the general principles of absolute-permissive-block signaling systems, when the signal location at the ends of the sidings are as illustrated in Fig. 1E, upon the meeting of two trains, the train entering the siding such as train B passes a danger signal such as signal 9, as there is no distinctive signal indication provided for the movement of the train into the siding. The signal 9 governing entrance to the siding 24 is put to stop as soon as the track switch at either end of the siding is operated to a reverse position. This is accomplished in an obvious manner (see Fig. 2B) in accordance with the shunting of the track section by the switch circuit controller. For example, the operation of the track switch at the right-hand end of passing siding 24 to its reverse position closes an obvious circuit by the shifting of contact 250 of the switch circuit controller for the track switch involved to shunt the track section 8-9T and put the entering signals 8 and 9 governing entrance to such track section to stop. It is, of course, to be understood that other signaling arrangements can be provided for governing traffic over the track switch, such for ex-

ample, as the use of a short detector track section for each of the track switches of each passing siding in a manner well known to those familiar with the art. Under such conditions, of course, there are separate entering signals usually provided for entrance of a train into the siding section on the main track, or into the siding.

It has been pointed out in considering singly the passage of a train in each direction that the entrance of a train, such as train A or train B shown in Fig. 1D, into the stretch of main track within the siding limits causes a 90 code to be transmitted through the track section in the rear to provide a less restrictive signal indication two blocks in the rear than would be provided if such train were travelling in the opposite direction. More specifically, it will be noted that, in the rear of the train A, a 90 code is transmitted through track section 6-7T for the caution indication of signal 6, and such 90 code at the signal 6 causes the transmission of a 180 code in the rear of such signal for the clearing of signal 4. From the circuits which have been described, it will be apparent that the 90 code is transmitted through the block in the rear of train A rather than a 60 code because the stick relay 8S (see Fig. 2A) for east bound traffic has been picked up. If such relay were not picked up as would be the case if track section 8-9T were occupied by a west bound train instead of an east bound train, a 60 code would be transmitted through track section 6-7T, and a 90 code would be transmitted through track section 4-5T to cause signal 4 to display a caution indication.

Upon considering the circuits which have been described for the control of the stick relay 8S, for example, it will be noted that such relay can be picked up only when an east bound train is in approach of signal 8 and the track switch at the left-hand end of track section 8-9T is in its normal position. Therefore, if the switch should be thrown to a reverse position for the entrance of a train into the siding 24, the stick relay 8S would be immediately dropped away, and the dropping away of such relay would select that after the track section 6-7T would become unoccupied in the rear of the train, a 60 code would be transmitted through that track section to cause the transmission of a 90 code through the track section 4-5T for the control of signal 4. Although the circuits are not shown for such code transmission, it will be apparent from the description of the transmission of signal control codes through track sections 10-11T and 12-13T how much transmission is effected.

In Fig. 1E, it is illustrated, upon the meeting of the trains A and B, how the release of the stick relay 9S (See Fig. 2B) (controlled in a manner similar to that described for relay 8S for the opposite direction of traffic) upon the entrance of the train B into the siding, is effective to provide full restrictive opposing signal protection for the east bound train A after the train B has entered the siding and the track switch has been properly positioned to allow further progress of the east bound train A. Such is true, irrespective of whether train B has arrived ahead of train A or vice versa, as the reversal of the track switch at the right-hand end of the siding 24 definitely causes the release of the stick relay 9S if such relay has had an opportunity to be picked up. Such release is, of course, effected in accordance with the opening of both the pick-up and stick circuits for the relay 9S by the shifting of contact 250 of the switch circuit controller for the

track switch at the right-hand end of siding 24. Such track switch, of course, can be thrown to its normal position following the passage of the train B into the siding without causing the stick relay 9S to be picked up, because the conditions necessary for the closing of the pick-up circuit for such relay are no longer satisfied.

Following trains.—Although the passage of following trains has not been considered in detail, the signal indications provided in the rear of east bound and west bound trains have been described, and the nature of the present invention is such that those indications described are the true indications that would be provided in advance of a following train. It will be, therefore, apparent from the description as it has been set forth, and from the diagrammatical illustrations as shown in Figs. 1A, 1B, 1C, 1D and 1E, that the signal indications provided for following trains under the traffic conditions most commonly encountered in practice are such as to provide a caution signal for governing entrance to the first block in the rear of a train, and a clear signal for governing entrance to the second block in the rear of a train. Such indications are provided in the rear of a train, irrespective of which track section of the track layout in this embodiment of the present invention such train occupies.

Having described a signaling system for a particular typical track layout as one specific embodiment of the present invention, it is desired to be understood that this form is selected for the purpose of facilitating in the disclosure of the invention rather than to limit the number of forms which the invention may assume, and it is to be further understood that various modifications, adaptations, and alterations may be applied to the specific form shown to meet the requirements of practice, without in any manner departing from the spirit or scope of the present invention except as limited by the appended claims.

What I claim is:

1. In a block signaling system of the character described for a stretch of main track having associated therewith two passing sidings separated by a plurality of blocks, each siding having a leaving signal for governing traffic therefrom toward the other siding; track circuit code communication means for each of the blocks effective to communicate by continuous distinctive track circuit codes selected signal controls from a given leaving signal to the opposing leaving signal, the track circuit codes employed being composed of impulses occurring at a continuous rate but being distinctive because of the frequency of reversal of the polarity of the impulses; signal control selecting means at said given signal effective to select one control for communication to the opposing leaving signal if there is no train in the rear of said given signal, and effective to select another control for communication to the opposing leaving signal if there is a train in the rear of said given signal; and signal control means at said opposing leaving signal operative to cause such signal to indicate clear when said one control is selected, and operative to cause such signal to indicate caution when said another control is selected.

2. In an absolute permissive block signaling system for a stretch of single track having associated therewith two passing sidings separated by a plurality of blocks, there being a leaving signal for each siding for governing traffic there-

from toward the other siding; track circuit code communication means for each of the blocks effective to communicate by continuous distinctive track circuit codes selected signal controls from a given leaving signal to the opposing leaving signal, the track circuit codes employed being composed of time spaced impulses occurring at a constant rate, different series of polar impulses being formed for providing the various distinctive codes by varying the frequency of reversal of the polarity of the impulses employed; a stick relay at the location of said given signal; circuit means for energizing said stick relay when a train is in the rear of said given signal, only if such train is traveling in a particular direction; signal control selecting means at said given signal effective to select one signal control for communication by track circuit code to the opposing leaving signal if there is a train in the rear of said given signal and said stick relay is energized, and effective to select another control for communication by track circuit codes to the opposing leaving signal if said stick relay is dropped away and if there is a train in the rear of said given signal; and signal control means at said opposing leaving signal effective to cause such signal to indicate clear when said one control is selected, and effective to cause such signal to indicate caution when said another control is selected.

3. In an absolute permissive block signaling system for a stretch of single track divided into blocks and having a passing siding and first and second signals governing approach to the siding for a given direction of traffic; track circuit code communication means for each of the blocks effective to communicate by selected continuous codes of impulses transmitted at a constant rate, various distinctive signal controls through the blocks in advance of the respective signals, the various distinctive codes employed being formed by different frequencies of reversal of polarity of the impulses forming the pattern of the code, code selecting means for the block in advance of the first signal effective to select one frequency of polarity reversal for the impulses transmitted through that block to such signal if the second block in advance of that signal is occupied by a train proceeding at said given direction, such code selecting means being effective to select another frequency of polarity reversal for the impulses transmitted through that block to such signal if the third block in advance of the signal is occupied by an opposing train; signal control means at said first signal operable to cause such signal to indicate caution when said one frequency or said another frequency has been selected; code selecting means for the block in advance of the second signal effective to select a particular code for transmission through that block to such signal if said first signal is at caution, only if said another frequency has been selected for transmission through the block in advance of said first signal; and signal control means for said second signal operable to cause that signal to indicate caution when said particular code has been selected.

4. In an absolute permissive block signaling system for a stretch of single track having first and second passing sidings a plurality of blocks apart, the first siding having an entering signal governing traffic in the direction of the second siding; track circuit code communication means for each of several blocks in advance of said signal for communicating by continuous distinctive polar track circuit codes various selected con-

trols to said signal, the impulses of the codes employed being transmitted at a constant rate and the various distinctive codes being selectively formed by the polarity of the impulses employed, certain of the codes being distinctive because of the frequency of reversal of polarity of the code impulses; track circuit code selecting means for the first block beyond the first siding effective upon passage of a train from said second siding toward said first siding for selecting a particular distinctive code for transmission to the first siding; signal control selecting means for the first block beyond the first siding effective to select one signal control for transmission to said signal if said stretch of track is unoccupied by a train, and effective to select another signal control for communication to said signal when said particular distinctive code has been selected, only if said first block is unoccupied by a train opposing said signal; and signal control means at said signal operative to cause such signal to indicate clear when said one control has been selected, to indicate caution when said another control has been selected, and to indicate danger when an opposing train occupies said first block beyond the first siding.

5. In a block signaling system of the character described for a stretch of single track having first and second passing sidings a plurality of blocks apart, the first siding having entering signals governing traffic in the direction of the second siding; track circuit code communication means for each of several blocks in advance of such signal for communicating by distinctive track circuit codes various selected controls to said signal, the impulses of the code impressed being transmitted at a constant rate and the various distinctive codes being selectively formed by the polarity of the impulses transmitted, certain of the codes being distinctive because of the frequent reversal of the polarity of the impulses; a stick relay for the first block beyond the first siding; circuit means for picking up said stick relay when said first block is occupied by a train, only if such train is proceeding toward said second siding; track circuit code selecting means for said first block effective to select one code for transmission to said signal if that block is occupied by a train and said stick relay is picked up, and effective to select another code for transmission to said signal if that block is occupied by a train and said stick relay is de-energized; and signal control means at said signal effective to cause such signal to indicate caution when said one code is selected and effective to cause such signal to indicate danger when said another code is selected.

6. In a signaling system of the character described for a stretch of track divided into track sections, a track circuit for a given one of the track sections, a source of current at one end of said track circuit, a circuit interrupter at said one end of said track circuit operable to form time spaced periods of energization by intermittently interrupting the flow of current in a circuit from a source of energy at a constant rate, an electro-responsive code transmitter at said one end of said track circuit controlled by said circuit interrupter and operable to apply to such track circuit an impulse of current of one polarity or the other from said source for each period of energization created by said circuit interrupter, polarity selecting circuit means operable in accordance with traffic conditions to

select any one of a plurality of different rates of transmission of impulses of a particular polarity by said code transmitter, rates less than the rate formed when all impulses are of said particular polarity being obtained by spacing the impulses of said particular polarity by one or more impulses of the opposite polarity, and a code receiver at the opposite end of said track circuit operable to be distinctively conditioned in accordance with each of the respective code rates formed by impulses of said particular polarity in said track circuit.

7. In a signaling system for railroads for a stretch of track divided into track sections; a track circuit for a given one of the track sections; a code transmitter at one end of said track circuit operable to selectively transmit through the track circuit different selected controls by distinctive series of continuous track circuit time spaced impulses or groups of impulses, the impulses of the different series being transmitted at a predetermined rate, and the different series being rendered distinctive because of a selected frequency of occurrence of impulses of a particular polarity spaced by impulses of the opposite polarity; and a code receiver at the other end of said track circuit distinctively responsive to the rate of occurrence of impulses of a particular polarity in said track circuit.

8. In a signaling system of the character described for a stretch of track divided into track sections; a track circuit for a given one of the track sections; a driven code transmitter at one end of said given track section operable to impress impulses at different selected code rates upon the track circuit, such rates being selected in accordance with traffic conditions; an inverse code transmitter at the other end of the track circuit controlled in accordance with traffic conditions and at times responsive to each impulse impressed upon the track circuit at said one end to impress a following impulse upon such track circuit, such inverse code transmitter being effective to at other times transmit only one impulse for each two impulses transmitted from the opposite end of the track section by said driven code transmitter; and a code receiver for each end of the track circuit distinctively responsive to the different rates of impulses impressed on the track circuit by the code transmitter at the opposite end of the track section.

9. In a signaling system for railroads for a stretch of track divided into track sections; a track circuit for one of the track sections; a driven code transmitter at one end of the track circuit normally active to continuously impress time spaced impulses upon such track circuit at different code rates selected in accordance with traffic conditions; an inverse code transmitter at the other end of the track circuit active in response to each impulse impressed upon said track circuit at said one end to impress a following impulse upon said track circuit, such inverse code transmitter being at times selected by traffic conditions effective to transmit but one impulse for each three impulses transmitted from said one end of the track section; and a code receiver for each end of the track circuit distinctively responsive to each of the different code rates transmitted through the track section from the code transmitter at the opposite end.

10. In a signaling system for railroads for a stretch of track divided into track sections; a track circuit for a given one of the track sections; a driven code transmitter at one end of

said track circuit effective to impress impulses at different code rates upon said track circuit in accordance with traffic conditions; an inverse code transmitter at the other end of said track circuit operably responsive to the impulses impressed on said track circuit by the driven code transmitter at said one end to impress upon such track circuit at the other end an impulse of selected polarity following either only some or all of the impulses by which such inverse code transmitter is actuated, the polarity of the impulses of the inverse code applied and the frequency of application of these inverse impulses being selected at said other end of said track circuit in accordance with traffic conditions to form distinctive series of impulses; and a code receiver for each end of said track circuit distinctively responsive to the different rates of application of impulses of a particular polarity impressed upon said track circuit by the code transmitter at the opposite end thereof.

11. In a signaling system for railroads for a stretch of track divided into track sections; a track circuit for a given one of the track sections; a pulsing device at one end of said track circuit normally actuated at a predetermined rate; a driven code transmitter at said one end of said track circuit operable to follow the pulsing of said device and impress upon said track circuit an impulse of selected polarity for each pulse of said device, the polarity selected being such as to form a selected distinctive series of polar impulses in the track circuit, such series comprising all impulses of a particular polarity, or comprising impulses of a particular polarity frequently spaced by at least one impulse of the opposite polarity, selected in accordance with traffic conditions; an inverse code transmitter at the opposite end of said track circuit operable in response to each impulse impressed upon said track circuit at said one end to at times impress upon said track circuit an impulse of selected polarity following the impulse by which such transmitter is actuated, the polarity forming a selected distinctive series of impulses in said track circuit, such series comprising all impulses of one polarity or the other, or at other times comprising impulses of a particular polarity spaced to occur at a rate less than the rate of transmission of impulses by the driven code transmitter at the opposite end of the track section, the selection of the series of impulses for transmission being effected in accordance with traffic conditions; and a code receiver for each end of said track circuit distinctively responsive to each different series of impulses impressed upon said track circuit by the code transmitter at the opposite end thereof.

12. In a signaling system of the character described; a pulsing device for creating pulses at one predetermined rate only; a stepping relay bank including a plurality of stepping relays of which the last constitutes an execution relay; means controlled by traffic conditions to under certain traffic conditions cause all of said stepping relays to be sequentially operated one for each pulse of said pulsing device; and then repeated, and to under other traffic conditions cause some of said stepping relays exclusive of said execution relay to be excluded from said stepping bank and to cause the remaining stepping relays to be sequentially operated one for each pulse of said pulsing device, and then repeated; a track circuit; and means for creating

an impulse in said track circuit for each operation of said execution relay.

13. In a signaling system of the character described; a section of track; a pulsing device at one end of said section for transmitting impulses at one predetermined rate through the track rails of said section to the other end; a stepping relay bank including a plurality of stepping relays of which the last constitutes an execution relay at the other end of said section; means controlled by traffic conditions to under certain traffic conditions cause all of said stepping relays to be sequentially operated one for each impulse transmitted, and then repeated, and to under other traffic conditions cause some of said stepping relays exclusive of said execution relay to be excluded from said stepping bank and to cause the remaining stepping relays to be sequentially operated one for each impulse transmitted, and then repeated; and means for creating an inverse impulse in said track circuit transmitted from said other end to said one end for each operation of said execution relay.

14. In a signaling system of the class described, a section of railway track, means at one end of said section for transmitting a driven code consisting of a plurality of impulses separated by "off" periods to the other end of said section, inverse coding means at the other end of said section which responds to each impulse of such driven code for transmitting an inverse code impulse during each "off" period of such driven code or during each alternate "off" period of such driven code depending on traffic conditions, traffic controlled means for controlling said inverse coding means to transmit inverse code impulses for either all or only alternate "off" periods, and code responsive means at said one end of said section distinctively responsive to inverse code impulses transmitted on all or on alternate "off" periods of said driven code.

15. In a signaling system of the class described; a section of railway track; means at one end of said section for transmitting a driven code consisting of a plurality of impulses separated by "off" periods to the other end of said section; inverse coding means at the other end of said section which responds to each impulse of such driven code for transmitting an inverse code impulse during each "off" period of such driven code, or during only some of said "off" periods and during such as do occur at equal time spaced intervals depending on traffic conditions; traffic controlled means for controlling said inverse coding means to transmit inverse code impulses for either all "off" periods or said some "off" periods which occur at equal time spaced intervals; and code responsive means at said one end of said section distinctively responsive to inverse code impulses transmitted on all or on said some equal time spaced "off" periods of said driven code.

16. In an absolute-permissive-block signaling system; the combination with a single track stretch connecting two passing sidings and divided into sections, track circuit code communicating means for each section including driven code transmitting means at one end of such section for transmitting code impulses of current of a particular polarity at any one of a plurality of different rates separated by "off" periods in one direction and including inverse code transmitting means at the other end of such section for transmitting inverse code impulses at different selected rates so correlated to the impulses of said driven

codes that the inverse code impulses fall in "off" periods of said driven codes irrespective of the rate of the driven code, means for selecting the rate of the code applied to each end of each track section in accordance with the code received at the adjacent end of the adjoining track section, a head-block signal at each end of said single track stretch for governing the movement of traffic into such stretch from that end and controlled by the code transmitted toward that signal in the track section in advance to clear that signal if the transmitted code is of a particular rate and to cause it to display caution if the transmitted code is of a different rate, and an intermediate signal for each head-block signal located in advance thereof and governing traffic in the same direction and controlled by codes in the track section in advance thereof and transmitted toward such intermediate signal so as to indicate clear if the transmitted code is of a particular rate and to indicate caution if the transmitted code is of a different rate.

17. In an absolute-permissive-block signaling system; the combination with a single track stretch connecting two passing sidings and divided into sections; track circuit code communicating means for each section including driven code transmitting means at one end of such section for transmitting code impulses of current of a particular polarity at any one of a plurality of different rates separated by "off" periods in one direction, including inverse code transmitting means at the other end of such section for transmitting inverse code impulses at different selected rates so correlated to the impulses of said driven codes that the inverse code impulses fall in "off" periods of said driven codes irrespective of the rate of the driven code and including code receiving means at the opposite end for each code transmitting means distinctively responsive to the transmitted code; means for selecting the code rates of the codes applied to each end of each track section in accordance with the code received by the receiving means at the adjacent end of the adjacent track section; a head-block signal at each end of said single track stretch for governing the movement of traffic into such stretch from that end and controlled by the code receiving means for the adjacent end of the track section in advance to clear that signal if the received code is of a particular rate and to cause it to display caution if the received code is of a different rate, and an intermediate signal for each head-block signal located in advance thereof and governing traffic in the same direction and controlled by code receiving means for the adjacent end of the track section in advance thereof to control such intermediate signal so as to indicate clear if the received code is of a particular rate and to indicate caution if the received code is of a different rate.

18. In an absolute-permissive-block signaling system, the combination with a single track stretch connecting two passing sidings and divided into sections, track circuit code communicating means for each section including driven code transmitting means at one end of each section for transmitting code impulses of current of a particular polarity at any one of a plurality of different rates separated by "off" periods in one direction and including inverse code transmitting means at the other end of such section for transmitting inverse code impulses at different selected rates so correlated to the impulses

of said driven codes that the inverse code impulses fall in "off" periods of said driven codes irrespective of the rate of the driven code, a head-block signal at each end of said single track stretch for governing the movement of traffic into such stretch from that end and controlled by the code transmitted toward that signal in the track section in advance thereof to clear that signal if the transmitted code is of a particular rate and to cause it to display caution if the transmitted code is of a different rate, an intermediate signal for each head-block signal located in advance thereof and governing traffic in the same direction and controlled by codes in the track section in advance thereof and transmitted toward such intermediate signal so as to indicate clear if the transmitted code is of a particular rate and to indicate caution if the transmitted code is of a different rate, a directional stick relay for each intermediate signal together with means for picking it up when a train passes that signal and for dropping it away when such train has passed the signal next in advance, and means for selecting the codes applied to the track section to the rear of each intermediate signal at the end adjacent such signal in accordance with the code transmitted to the adjacent end of the section in advance of such intermediate signal and also in accordance with the energized or deenergized condition of the associated directional stick relay.

19. In an absolute-permissive-block signaling system; the combination with a single track stretch connecting two passing sidings and divided into sections; track circuit code communicating means for each section including driven code transmitting means at one end of each section for transmitting code impulses of current of a particular polarity at any one of a plurality of different rates separated by "off" periods in one direction, including inverse code transmitting means at the other end of such section for transmitting inverse code impulses at different selected rates so correlated to the impulses of said driven codes that the inverse code impulses fall in "off" periods of said driven codes irrespective of the rate of the driven code and including code receiving means for each code transmitting means located at the opposite end of the same track section distinctively responsive to said codes; a head-block signal at each end of said single track stretch for governing the movement of traffic into such stretch from that end and controlled by the code receiving means for the adjacent end of the track section in advance to clear that signal if the code received by such code receiving means is of a particular rate and to cause it to display caution if the received code is of a different rate, an intermediate signal for each head-block signal located in advance thereof and governing traffic in the same direction and controlled by the code receiving means for the adjacent end of the track section in advance thereof and so as to indicate clear if the code received by such code receiving means is of a particular rate and to indicate caution if the received code is of a different rate, a directional stick relay for each intermediate signal together with means for picking it up when a train passes that signal and for dropping it away when such train has passed the signal next in advance; means for selecting the codes applied to the far end of the track section in advance of each intermediate signal in accordance with traffic conditions in advance thereof; and means for select-

ing the codes applied to the track section to the rear of each intermediate signal at the end adjacent such signal in accordance with the code received at the adjacent end of the section in advance of such intermediate signal and also in accordance with the energized or deenergized condition of the associated directional stick relay.

20. In an absolute-permissive-block signaling system; the combination with a single track stretch connecting two passing sidings each including a main track section and a side track; said single track stretch being divided into sections; track circuit code communicating means for each section including driven code transmitting means at one end of such section for transmitting code impulses of current of a particular polarity at any one of a plurality of different rates separated by "off" periods in one direction and including inverse code transmitting means at the other end of such section for transmitting inverse code impulses at different selected rates in the opposite direction and so correlated with the impulses of said driven codes that the inverse code impulses fall in "off" periods of said driven codes irrespective of the rate of such driven code; a head-block signal at each end of said single track stretch for governing the movement of traffic into such stretch from that end and controlled by the code transmitted toward that signal in the track section in advance thereof to clear that signal if the transmitted code is of a particular rate, to cause it to display caution if the transmitted code is of a different rate and to cause it to display stop if no code is transmitted; an intermediate signal for each head-block signal located in advance thereof and governing traffic in the same direction and controlled in accordance with codes in the track section in advance of such intermediate signal and transmitted toward such intermediate signal so as to indicate clear if the transmitted code is of a particular rate, to indicate caution if the transmitted code is of a different rate and to cause it to display stop if no code is transmitted; control means for selecting the rate of the code applied to each end of each track section in accordance with the code transmitted to the adjacent end of the adjacent track section, means including said control means and responsive to the presence of a train on the main track of one passing siding for controlling the codes transmitted away from such train in the track sections of the single track stretch in advance to cause the opposing signals in such single track stretch to indicate caution and to cause the removal of such codes to cause these signals to indicate stop upon movement of the train into said single track stretch.

21. In an absolute-permissive-block signaling system, the combination with a single track stretch connecting two passing sidings each including a main track section and a side track, said single track stretch being divided into sections, track circuit code communicating means for each section and for the main track of said passing sidings including driven code transmitting means at one end of such section for transmitting code impulses of current of a particular polarity at any one of a plurality of different rates separated by "off" periods in one direction and including inverse code transmitting means at the other end of such section for transmitting inverse code impulses at different selected rates in the opposite direction and so correlated with the impulses of said driven codes that the inverse

code impulses fall in "off" periods of said driven codes irrespective of the rate of such driven code, a head-block signal at each end of said single track stretch for governing the movement of traffic into such stretch from that end and controlled by the code transmitted toward that signal in the track section in advance thereof to clear that signal if the transmitted code is of a particular rate, to cause it to display caution if the transmitted code is of a different rate and to cause it to display stop if no code is transmitted, an intermediate signal for each head-block signal located in advance thereof and governing traffic in the same direction and controlled in accordance with codes in the track section in advance of such intermediate signal and transmitted toward such intermediate signal so as to indicate clear if the transmitted code is of a particular rate, to indicate caution if the transmitted code is of a different rate and to cause it to display stop if no code is transmitted, control means for selecting the rate of the code applied to each end of each track section in accordance with the code transmitted to the adjacent end of the adjacent track section, means including said control means and responsive to the presence of a train on the main track of one passing siding for controlling the codes transmitted away from such train in the track sections of the single track stretch in advance to cause the opposing signals in such single track stretch to indicate caution and to cause the removal of such codes to cause these signals to indicate stop upon movement of the train into said single track stretch, and means including said control means for selecting the code transmitted toward a head-block signal in the track section in advance thereof to cause such signal to indicate clear when the intermediate signal in advance thereof and governing traffic in the same direction indicates caution due to a departing train in advance thereof.

22. In an absolute-permissive-block signaling system, the combination with two single track stretches connected by a passing siding including a main track section and a side track, said single track stretches being divided into track sections, track circuit code communicating means for each section including driven code transmitting means at one end of such section for transmitting codes of impulses at different rates separated by "off" periods in one direction and including inverse code transmitting means at the other end of such section for transmitting inverse code impulses at different rates in the opposite direction and so correlated with the impulses of said driven codes that the inverse code impulses fall in "off" periods of said driven codes irrespective of the rate of such driven code, a head-block signal at each end of each single track stretch for governing the movement of traffic into such stretch from that end and controlled by the code transmitted toward that signal in the track section in advance thereof to clear that signal if the transmitted code is of a particular rate, to cause it to display caution if the transmitted code is of a different rate and to cause it to display stop if no code is transmitted, an intermediate signal for each head-block signal located in advance thereof and governing traffic in the same direction and controlled in accordance with codes in the track section in advance of such intermediate signal and transmitted toward such intermediate signal so as to indicate clear if the transmitted code is of

a particular rate, to indicate caution if the transmitted code is of a different rate and to indicate stop if no code is transmitted, an entering signal at each end of said passing siding for governing the movement of traffic out of the adjacent single track stretch at the adjacent end and controlled in accordance with codes in the main track section of the passing siding transmitted toward such signal so as to indicate clear if such code is of a particular rate, so as to indicate caution if the code is of a different rate and so as to indicate stop if no such code is transmitted, control means for selecting the rate of the code applied to each end of each track section in accordance with the code transmitted to the adjacent end of the adjacent track section, means including said control means and responsive to the entrance of an opposing train into the far end of the track section in advance of a head-block signal of said passing siding to select the codes in track sections in advance of such train and transmitted away from such train to cause the entering signal at the opposite end of such passing siding to display caution and to cause the intermediate signal in the rear thereof and governing traffic in the same direction to indicate caution, and means including said control means and responsive to the movement of said train onto the main track section of said passing siding selecting the codes transmitted away from such train in the track sections of the single track stretch in advance to cause the opposing intermediate signal to continue to indicate caution and to cause the head-block signal in the rear thereof and governing traffic in the same direction to be operated to indicate caution and to cause the removal of such codes from the track sections of such single track stretch to cause these latter two signals to indicate stop upon movement of the train into said single track stretch.

23. In an absolute-permissive-block signaling system, the combination with two single track stretches connected by a passing siding including a main track section and a side track, said single track stretches being divided into track sections, track circuit code communicating means for each section including driven code transmitting means at one end of such section for transmitting codes of impulses at different rates separated by "off" periods in one direction and including inverse code transmitting means at the other end of such section for transmitting inverse code impulses at different rates in the opposite direction and so correlated with the impulses of said driven codes that the inverse code impulses fall in "off" periods of said driven codes irrespective of the rate of such driven code, a head-block signal at each end of each single track stretch for governing the movement of traffic into such stretch from that end and controlled by the code transmitted toward that signal in the track section in advance thereof to clear that signal if the transmitted code is of a particular rate, to cause it to display caution if the transmitted code is of a different rate and to cause it to display stop if no code is transmitted, an intermediate signal for each head-block signal located in advance thereof and governing traffic in the same direction and controlled in accordance with codes in the track section in advance of such intermediate signal and transmitted toward such intermediate signal so as to indicate clear if the transmitted code is of a particular rate, to indicate caution if the

transmitted code is of a different rate and to indicate stop if no code is transmitted, an entering signal at each end of said passing siding for governing the movement of traffic out of the adjacent single track stretch at the adjacent end and controlled in accordance with codes in the main track section of the passing siding transmitted toward such signal so as to indicate clear if such code is of a particular rate, so as to indicate caution if the code is of a different rate and so as to indicate stop if no such code is transmitted, control means for selecting a rate of the code applied to each end of each track section in accordance with the code transmitted to the adjacent end of the adjacent track section, means including said control means and responsive to the entrance of a train into the end of one of said stretches remote from said passing siding to select the codes in track sections in advance in said stretch, for the main track section of said passing siding and for the first track section in the single track stretch in advance of said siding and transmitted away from such train to cause the opposing intermediate signal and the opposing head-block signal in said section to indicate stop and the entering signal at the opposite end of such passing siding to display caution and to cause the intermediate signal in the rear thereof and governing traffic in the same direction to indicate caution, means including said control means and responsive to the movement of said train past the opposing intermediate signal in said stretch selecting the codes transmitted away from such train in the track sections in advance to cause the opposing entering signal to indicate stop and to cause the intermediate signal in the rear thereof to continue to indicate caution, and means including said control means for selecting the codes for the track sections of such single track stretch in advance and transmitted away from such train to cause the opposing intermediate signal to continue to indicate caution and the head-block signal in the rear thereof to change from clear to caution as such train enters the main track section of such passing siding.

24. In an absolute-permissive-block signaling system, the combination with two single track stretches connected by a passing siding including a main track section and a side track, said single track stretches being divided into track sections, track circuit code communicating means for each section including driven code transmitting means at one end of such section for transmitting codes of impulses at different rates separated by "off" periods in one direction and including inverse code transmitting means at the other end of such section for transmitting inverse code impulses at different rates in the opposite direction and so correlated with the impulses of said driven codes that the inverse code impulses fall in "off" periods of said driven codes irrespective of the rate of such driven code, a head-block signal at each end of each single track stretch for governing the movement of traffic into such stretch from that end and controlled by the code transmitted toward that signal in the track section in advance thereof to clear that signal if the transmitted code is of a particular rate, to cause it to display caution if the transmitted code is of a different rate and to cause it to display stop if no code is transmitted, an intermediate signal for each head-block signal located in advance thereof and governing traffic in the same direction and con-

trolled in accordance with codes in the track section in advance of such intermediate signal and transmitted toward such intermediate signal so as to indicate clear if the transmitted code is of a particular rate, to indicate caution if the transmitted code is one of two different rates and to indicate stop if no code is transmitted, an entering signal at each end of said passing siding for governing the movement of traffic out of the adjacent single track stretch at the adjacent end and controlled in accordance with codes in the main track section of the passing siding transmitted toward such signal so as to indicate clear if such code is of a particular rate, so as to indicate caution if the code is one of two different rates and so as to indicate stop if no such code is transmitted, control means for selecting the rate of the code applied to each end of each track section in accordance with the code transmitted to the adjacent end of the adjacent track section, means including said control means and responsive to the entrance of an opposing train into the far end of the track section in advance of a head-block signal of said passing siding to select the codes in track sections in advance and transmitted away from such train to cause the entering signal at the opposite end of such passing siding to display caution and to cause the intermediate signal in the rear thereof and governing traffic in the same direction to indicate caution due to the transmission of a code of the first of said two rates thereto to in turn cause the head-block signal in the rear thereof to continue to indicate clear, and means including said control means and responsive to the movement of said train onto the main track section of said passing siding selecting the codes transmitted away from such train in the track sections of the single track stretch in advance to cause the opposing intermediate signal to continue to indicate caution but now due to the transmission of a code of the second of said two rates thereto to in turn cause the head-block signal in the rear thereof to indicate caution and to cause the removal of such codes from the track sections of such single track stretch to cause these latter two signals to indicate stop upon movement of the train into said single track stretch.

25. In a signaling system of the character described for a stretch of railway track including a track section; a pulsing device for creating pulses at one predetermined rate only; a track circuit for said track section; track circuit code transmitting means controlled by said pulsing device for impressing upon said track circuit either a code comprising one current impulse for each pulse created by said pulsing device, a code comprising one current impulse for each alternate pulse created by said pulsing device or a code comprising one current impulse for each third pulse created by said pulsing device as selected by traffic conditions; and electro-responsive means effective to select any one of said codes for transmission in accordance with traffic in the portion of track adjacent said track section.

26. In a signaling system of the character described for a stretch of railway track including a track section; a pulsing device for creating pulses at one predetermined rate only; a track circuit for said track section; track circuit code transmitting means controlled by said pulsing device for impressing upon said track

circuit either a code comprising one current impulse for each pulse created by said pulsing device or a code comprising one current impulse for each alternate pulse created by said pulsing device as selected by traffic conditions, and electro-responsive means effective to select any one of said codes for transmission in accordance with traffic in the portion of track adjacent said track section.

27. In a coded track circuit signal system for single track railroads, a siding track section opposite a passing siding and an end section of a stretch of single track extending in one direction from said siding section, a head-block signal at the siding end of said end section for governing train movement into the stretch of single track, an entering signal at the other end of the siding section governing train movement in the same direction, means for transmitting over the track rails of said end section toward said head-block signal one kind of a code under certain conditions and a code of different kind under other conditions, means associated with said head-block signal for clearing it in response to said code of one kind but not the other kind, and means responsive to the presence of said codes of either kind in said end section for governing the clearing of said entering signal by means of code transmitted over the track rails of the siding section, said means acting to cause said entering signal to indicate stop when a train in the stretch of single track approaching said siding and holding said head-block signal at stop enters said end section and stops transmission of either code to said head-block signal.

28. A system of signaling for single track railroads employing coded track circuits and comprising, a siding track section opposite a passing siding and a stretch of single track extending from each end thereof to an adjacent siding, each of said stretches of single track having an end track section adjacent said siding section, a head-block signal at each end of the siding section governing train movement into the corresponding stretch of single track, means associated with each stretch of single track and normally acting when that stretch is not occupied by a train for transmitting code toward said siding section for governing the indications of the corresponding head-block signal, said means acting upon the entrance of a train into the corresponding stretch for distinctively governing the code in the end section to put the opposing head-block signal to stop while maintaining coding in said end section to detect its occupancy by a train, an entering signal at each end of said siding section for governing train movement into that section, and means responsive to the cessation of the code in the end section toward the siding when a train approaching said siding enters said end section for causing the opposing entering signal to indicate stop.

29. In a coded track circuit system of automatic block signaling for single track railroads including a siding track section adjacent a passing siding with stretches of single track extending therefrom and each stretch of single track having an end section adjacent the siding section, a head-block signal at each end of the siding section for governing train movement into the stretch at that end, entering signals at opposite ends of the siding section for governing train movements into such section in opposite

directions, intermediate signals in the rear of each entering signal for governing train movement through the corresponding end section toward the siding section, coded track circuit apparatus associated with each track section and said siding section for transmitting different codes in each direction through such section for controlling the indications of the signals at the opposite ends thereof and normally acting to cause all such signals to display clear indications, means responsive to the entrance of a train into either stretch of single track for causing a distinctive code to be transmitted through the corresponding end section to the opposing head-block signal for causing that signal to display stop and also for causing distinctive codes to be transmitted through said siding section and the remote end section to cause the opposing entering signal and the distant intermediate signal to display caution indications, and means responsive to the presence of a train in either end section thereby causing the cessation of code transmission toward the head-block signal for the corresponding end of the siding, for preventing the transmission of all codes to the opposing entering signal to cause that signal to display a stop indication and thereby provide siding overlap control.

30. In a coded track circuit system of automatic block signaling for single track railroads including a siding track section adjacent a passing siding with stretches of single track extending therefrom and each stretch of single track having an end section adjacent the siding section, a head-block signal at each end of the siding section for governing train movement into the stretch at that end, entering signals at opposite ends of the siding section for governing train movements into such section in opposite directions, intermediate signals in the rear of each entering signal for governing train movement, coded track circuit apparatus associated with each track section and said siding section for transmitting code pulses in both directions for controlling indications of the signals governing traffic over that section, means responsive to the entrance of a train into either single track stretch for acting through said coded track circuit apparatus to cause the opposing head-block signal to display a stop indication without stopping the transmission of code pulses toward that signal and also to cause the intermediate signal governing traffic into the remote end section to display a caution indication, and means responsive to the cessation of transmission of code pulses toward either head-block signal upon the entrance of a train into the corresponding end section for acting through said coded track circuit apparatus to cause the opposing entering signal to display a stop indication for providing siding overlap control.

31. In a coded track system of automatic block signaling for single track railroads including a siding track section adjacent a passing siding with stretches of single track extending in opposite directions therefrom and each stretch of single track having an end track section adjacent the siding, entering signals at opposite ends of the siding section for governing traffic into said siding section in opposite directions, an intermediate signal in the rear of each entering signal for governing traffic over the corresponding end section towards the siding section, coded track circuit apparatus associated with each track sec-

tion and said siding section for transmitting codes in opposite directions for controlling said signals, means responsive to the entrance of a train into either stretch of single track and acting through said coded track circuit apparatus to control the opposing entering signal and the intermediate signal in the rear thereof to indicate caution so as to provide a double distant caution indication, and means responsive to the presence of a train in either end section and acting through said coded track circuit apparatus to control the opposing entering signal to stop while permitting its own entering signal to be controlled through said coded track circuit apparatus in accordance with the presence and location of a train in the other stretch of single track so as to provide siding overlap control.

32. In a signaling system for railroads for a stretch of track divided into a plurality of track sections, a coded track circuit organization for each track section including a pulsing device at one end of said track section normally active to operate at a predetermined rate, a source of energy at said one end of said track section, an electro-responsive code transmitter at said one end of said track section electrically operable to follow the operation of said device to impress only a single current impulse of selected polarity from said source to said track circuit for each operation of said pulsing device, a polarity selecting means dependent upon traffic conditions for selecting the polarity of each successive impulse of current applied by said transmitter, such polarity selecting means being operable to select a series of impulses of a particular polarity for transmission under one traffic condition and operable to select a series of impulses of said particular polarity spaced at intervals by at least one impulse of the opposite polarity under a different traffic condition, whereby the impulses of said particular polarity are transmitted at different code rates for different traffic conditions although the impulses of each series are transmitted at the same rate irrespective of the polarity of the impulses selected for such series, and a code receiver for the other end of said track circuit distinctively responsive to the rate of reception of the impulses of said particular polarity as included in the different series of polar impulses impressed by said transmitter.

33. In a signaling system of the character described for a stretch of track divided into track sections, a track circuit for one of the track sections, a pulsing device at one end of the track circuit normally active to create pulses at a predetermined rate, a code execution relay, electro-responsive means associated with said execution relay and governed in accordance with traffic conditions in advance of said track section, circuit means governed by said traffic controlled electro-responsive means for energizing said code execution relay for each pulse of operation of said pulsing device under certain traffic conditions, and for energizing said code execution relay for only every alternate pulse of said pulsing device under different traffic conditions, and a code transmitter relay responsive each time said code execution relay is energized to impress an impulse of current upon said track circuit from an associated source of energy.

34. In a coded track circuit signaling system for single track railroads, the combination with a siding section of track adjacent a passing siding and stretches of single track extending in opposite directions therefrom to other sidings, each of

said stretches including an end section adjacent said siding section, an entering signal at each end of said siding section governing traffic into said section, a head-block signal at each end of each stretch of single track for governing traffic in opposite directions into that stretch, means normally acting to provide driven and inverse codes in each stretch of single track for clearing the head-block signals at both ends thereof, and means associated with the end of each end section adjacent said siding section differently controlled through the medium of said codes in response to the presence of a train entering the corresponding stretch and entering the corresponding end section approaching said siding section, said means acting to govern the transmission of distinctive codes over said siding section to cause the entering signal at the opposite end of the siding section to indicate caution when the train enters the stretch but to indicate stop when the train enters the end track section.

35. In a coded track circuit system of automatic block signaling for single track railroads including a siding track section adjacent a passing siding with stretches of single track extending in opposite directions therefrom and each

stretch of single track having an end track section adjacent the siding, entering signals at opposite ends of the siding section for governing traffic into said siding section in opposite directions, an intermediate signal in the rear of each entering signal for governing traffic over the corresponding end section toward the siding section, coded track circuit apparatus associated with each track section and said siding section for transmitting different codes through such section to control the indications of the signals governing traffic thereof, means responsive to the entrance of a train into either stretch of single track for causing distinctive codes to be transmitted through said siding section and the remote end section to cause the remote entering signal to display a caution indication and the distant intermediate signal in the rear thereof to also display a caution indication providing such remote end section is unoccupied, and means responsive to the presence of a train in either end section for preventing the transmission of all codes to the opposing entering signal for causing that signal to display a stop indication and there-by provide siding overlap control.

SEDGWICK N. WIGHT.
